APPARATUS FOR PACKAGING FIBROUS ARTICLES

William D. Young, Greenville, S. C., assignor of forty per cent to Dorothy R. Young, twenty per cent to Betty Young Shorey, twenty per cent to Jean Young Martin, and twenty per cent to Nancy Lou Young, all of Greenville, S. C.

Application June 5, 1948, Serial No. 31,353

121 Claims. (Cl. 19—144.5)

This invention relates to packaging machinery and more especially to a machine for forming and compressing articles, such as sanitary napkins into a cylindrical shape and inserting the same into tubular containers for advancing them to another machine to have the open ends of the tubular containers sealed in a conventional manner.

It is an object of this invention to provide a pair of conveyors, one of them being a belt conveyor and the other a chain conveyor, said conveyors being disposed in side by side relation to each other so that the sanitary napkins are fed from another machine on the belt conveyor and are picked up by the operators and placed on the chain conveyor. The chain conveyor will pass into the machine and injector clips will engage the sanitary napkins, moving the same off the chain conveyor onto combination folding and forming dies each having a groove extending therethrough in alignment with the longitudinal axis of the sanitary napkins.

A folding means then engages the top central portion of each of the sanitary napkins longitudinally and moves the same downwardly into the folding and forming dies at which time the folding means are withdrawn automatically and then the forming means move downwardly into the same groove and form each of the sanitary napkins into a substantially cylindrical shape. The napkins are then moved out of the forming dies by compressing rods and simultaneously with the movement of the napkins out of the forming dies, tubular containers are moved toward the compressing means. The tubular containers and the sanitary napkins each enter opposite ends of bores disposed in a turret member and the ends of the back-up shafts which move the tubular containers into the turret, cover one of the ends of each of the tubular containers, thus causing the compressing rods which are moving towards the opposite ends of the tubular containers to compress the sanitary napkins longitudinally within the tubular containers.

It is another object of this invention to provide means for rotating the turret, in step by step relation, 90 degrees at a time, to where, when the tubular containers with the compressed sanitary napkins therein have moved 180 degrees from the position in which they were originally inserted in the turret, the openings, in which said tubular containers containing the sanitary napkins have been inserted, are disposed in alignment with an ejector mechanism which will eject the containers with the sanitary napkins therein, from the turret.

It is another object of this invention to provide conveyor means for carrying the discharged containers out of the machine to where they may be picked up for further processing by another operator.

It is another object of this invention to provide means for directing a blast of air to each of the openings in the turret after the containers have been discharged therefrom, to thereby remove any lint or other foreign matter which may have accumulated in the openings in said turret during the process in which the tubular containers and

2

the sanitary napkins were inserted and discharged from the turret.

Some of the objects of the invention having been stated, other objects will appear as the description proceeds when taken in connection with the accompanying drawings, in which:

Figure 1 is a front elevation of the machine showing a portion of a conveyor for feeding articles disposed remotely from the machine to the machine;

10 Figure 2 is a side elevation looking from the right-hand side of Figure 1, toward the left, and showing the discharge end of the discharge conveyor;

Figure 3 is an elevation looking from left to right in Figure 1, partly in section and being taken along the line 15 3—3 in Figure 1;

Figure 3-A is a vertical sectional view taken along the line 3—A—3—A in Figure 1 and showing the driving means for the machine, which are omitted from Figure 3, for purposes of clarity.

20 Figure 4 is a rear elevation of the machine looking at the opposite side of Figure 1 with parts broken away;

Figure 5 is a top plan view of the machine with parts broken away;

25 Figure 6 is a vertical sectional view of the conveyors, taken along the line 6—6 in Figure 1;

Figure 7 is a vertical sectional view taken along the line 7—7 in Figure 1 and showing the belt conveyor only;

Figure 8 is a vertical sectional view taken along the line 30 8—8 in Figure 5 and omitting the chain conveyor;

Figure 9 is a top plan view of a portion of the chain conveyor taken substantially along the line 9—9 in Figure 1;

Figure 10 is an inverted view of one of the transversely disposed trays on the chain conveyor;

35 Figure 11 is an elevation looking up at the lower end of Figure 9 and is taken substantially along the line 11—11 in Figure 9;

Figure 12 is a vertical sectional view through one of the transversely disposed trays on the chain conveyor, and being taken substantially along the line 12—12 in Figure 11;

40 Figure 13 is a vertical sectional view showing, schematically, the injector clips for removing the sanitary napkins from the chain conveyor, and being taken substantially along the line 13—13 in Figure 5;

Figure 14 is a view similar to Figure 13 but showing the movable parts in a different position;

45 Figure 15 is a view showing the central portions in Figures 13 and 14 with the movable parts in another position and showing the folding and forming means associated therewith;

Figure 16 is a view similar to Figure 15 but showing the parts in still another position;

50 Figure 17 is an enlarged view of the guiding means associated with the sanitary napkin injector clips and of the central portions of Figures 13, 14, 15 and 16 with parts omitted;

Figure 18 is an isometric view showing a part of Figure 17;

55 Figure 19 is an elevation looking at the opposite side of Figure 17 and also being an enlarged view of the central portion of Figure 13;

Figure 20 is a top plan view showing the sanitary napkin injector means and being taken substantially along the line 20—20 in Figure 1;

60 Figure 21 is a vertical sectional view taken along the line 21—21 in Figure 20;

Figure 22 is a vertical sectional view showing the forming and folding means schematically and showing the cam which operates the folding means and being taken substantially along the line 22—22 in Figure 5;

70 Figure 23 is a view similar to Figure 22 but showing

the folding means in a different position relative to the forming means;

Figure 24 is a vertical sectional view of the forming and folding means and showing the cam which operates the forming means, both of them being shown schematically, and being taken substantially along the line 24—24 in Figure 5;

Figure 25 is a view similar to Figure 24 but showing the forming means in a different position relative to the folding means;

Figure 26 is an elevation of the folding and forming means as though removed from the machine and being taken substantially along the line 26—26 in Figure 24;

Figure 27 is a vertical sectional view taken along the line 27—27 in Figure 26;

Figure 28 is a sectional plan view taken along the line 28—28 in Figure 26;

Figure 29 is a view similar to Figure 26 but showing the movable parts in a different position and being taken along the line 29—29 in Figure 23;

Figure 30 is a view similar to Figure 29 but showing the movable parts in another position and being taken along the line 30—30 in Figure 25;

Figure 31 is a view showing the sanitary napkin as it is supported on one of the folding and forming dies preparatory for folding, and being taken along the line 31—31 in Figure 16;

Figure 32 is a view similar to Figure 31 but showing the folding means moving the sanitary napkin into one of the folding and forming dies;

Figure 33 is a view similar to Figure 32 but showing the parts as though advanced another step and showing the folding means withdrawn partially from one of the dies and the forming means moving downwardly towards the die;

Figure 34 is a view similar to Figure 33 but showing one of the forming means in its lowermost position in the die;

Figure 35 is a view similar to Figure 34 but showing the folding means withdrawn from one of the dies and showing the sanitary napkin therein as it is formed preparatory to being pressed into the turret;

Figure 36 is a vertical sectional view taken along the line 36—36 in Figure 34 and showing one of the compressing means about to enter one of the dies;

Figure 37 is a view similar to Figure 36 but showing a portion of the turret and the tubular container inserting means associated therewith;

Figure 38 is a view similar to Figure 37 but showing one of the sanitary napkins fully compressed in one of the bores in the turret as well as the tubular container which surrounds the sanitary napkin;

Figure 39 is a vertical sectional view showing, schematically, the turret and the means for directing a blast of air into some of the bores in the turret, and is taken substantially along the line 39—39 in Figure 3;

Figure 40 is a view similar to Figure 39 but showing the turret in a different position;

Figure 41 is a vertical sectional view taken substantially along the line 41—41 in Figure 1, with parts broken away;

Figure 42 is a vertical sectional view with parts broken away and being taken substantially along the line 42—42 in Figure 41;

Figure 43 is a view similar to Figure 42 showing the Geneva motion of the turret rotating means and associated parts, in a different position, and omitting parts, which are not pertinent to the Geneva motion, for purposes of clarity;

Figure 44 is a top plan view of the structure shown in Figure 43, but omitting the turret and being taken along the line 44—44 in Figure 43;

Figure 45 is a sectional plan view showing a portion of the Geneva motion and being taken along the line 45—45 in Figure 43;

Figure 46 is an elevation with parts in section and with parts broken away and being taken substantially along the line 46—46 in Figure 2;

Figure 47 is a vertical sectional view being taken substantially along the line 47—47 in Figure 46 and showing, schematically, the means for directing blasts of air through the bores in the turret;

Figure 48 is an elevation with parts in section and is taken substantially along the line 48—48 in Figure 47;

Figure 49 is a sectional plan view taken along the line 49—49 in Figure 48;

Figure 50 is an isometric view of the chutes down which the tubular containers roll by gravity into alignment with the inserting means and is taken substantially from a point indicated by the arrow 50 in Figure 4 and showing the chutes as though removed from the machine;

Figure 51 is a vertical sectional view taken substantially along the line 51—51 in Figure 50;

Figure 52 is an isometric view of the nest onto which the tubular containers fall by gravity from the chutes into alignment for being moved into the turret by the back-up shafts;

Figure 53 is a vertical sectional view taken substantially along the line 53—53 in Figure 4 showing, schematically, the back-up mechanism for inserting the tubular containers into the turret;

Figure 54 is a vertical sectional view taken substantially along the line 54—54 in Figure 1 showing the compressing mechanism for injecting the formed sanitary napkin into the turret;

Figure 55 is a view similar to Figure 54 but showing the movable parts in a different position;

Figure 56 is a vertical sectional view, with parts broken away, and showing the means for ejecting the filled containers from the turret, schematically, and being taken substantially along the line 56—56 in Figure 5;

Figure 57 is a view similar to Figure 56, but showing the movable parts in a different position, and omitting the back-up mechanism;

Figure 58 is a view similar to Figure 39, omitting the means for directing blasts of air to portions of the turret, but showing the discharge conveyor associated therewith;

Figure 59 is a view similar to the lower portion of Figure 57 but showing the movable parts in a different position;

Figure 60 is another view similar to the lower portion of Figure 57 but showing other of the parts in section;

Figure 61 is a vertical sectional view showing the discharge conveyor associated with the turret and being taken substantially along the line 61—61 in Figure 2;

Figure 62 is an isometric view of the frame on which the various parts of the machine are mounted but omitting the working parts of the machine for purposes of clarity;

Figure 63 is an elevation, with parts broken away, showing one of the containers, with a compressed article therein, after it has been discharged from this machine;

Figure 64 is an isometric view of one end of the article, showing a portion in section and parts of the covering broken away.

Referring more specifically to the drawings, the numeral 20 broadly designates a structural steel frame of the machine comprising spaced I-beams 21 and 22, which are supported on a floor F and, which have, spanning the distance therebetween, and welded at each end thereto, channel bars 23 and 24 to thus form a base for the machine frame. Mounted on the top surfaces of the I-beams 21 and 22, respectively, are horizontally disposed angle bars 25 and 26 which are secured thereto by any suitable means such as spot welding (Figure 62).

The angle bar 25 extends longitudinally of the I-beam 21 and has mounted on each end thereof the lower ends of vertically disposed angle bars 27 and 28. The upper

ends of the vertically disposed angle bars 27 and 28 are secured, as by welding, to opposite ends of a horizontally disposed angle bar 31 (Figures 2 and 62).

Disposed between the vertically disposed angle bars 27 and 28, in spaced relation to each other, are vertically disposed angle bars 32, 33 and 34, all of which are welded at their lower ends to the horizontally disposed angle bar 25 and are welded at their upper ends to the horizontally disposed angle bar 31. Disposed in spaced relation to the horizontally disposed angle bar 31 and mounted below the same, is a horizontally disposed channel bar 35 which is welded at one end, as observed in Figures 2 and 62, to the vertically disposed angle bar 28 and at its other end to the vertically disposed angle bar 34. Disposed below the angle bar 31, in spaced relation thereto, is a vertically disposed plate 36 having a horizontally disposed portion 37 which projects inwardly, or away from the observer, as viewed in Figures 2 and 62. This plate 36 is welded, at each end thereof, to the vertically disposed angle bars 33 and 34. Disposed below the plate 36, and in spaced relation thereto, is another plate 40 which is merely a bracing member between, and is welded to, the vertically disposed angle bars 33 and 34.

Disposed near the lower end of the vertically disposed angle bars 33 and 34, is a horizontally disposed angle bar 42 which is welded at each end to the vertically disposed angle bars 33 and 34 and has projecting downwardly, from the center thereof, a vertically disposed bar 43 which is welded at its upper end to the horizontally disposed angle bar 42 and at its lower end to the horizontally disposed angle bar 25.

Disposed above and in close proximity to the horizontally disposed angle bar 25 is an angle bar 44 the front end of which is welded to the vertically disposed angle bar 27 and the other end of which is welded to the vertically disposed angle bar 33. The angle bar 44 is also welded, intermediate its ends, to the vertically disposed angle bar 32.

By referring to Figures 1, 3 and 62, it may be observed that the angle bar 26 has, projecting upwardly from each end thereof, angle bars 45 and 46 which are connected together at their upper ends by a horizontally disposed angle bar 47 and all of which are welded together. Disposed centrally of the horizontally disposed angle bars 26 and 47, and spanning the distance therebetween, is a vertically disposed angle bar 50 which is welded at each end thereof to the angle bars 26 and 47.

Disposed between the vertically disposed angle bars 46 and 50, welded to the horizontally disposed angle bar 26 and projecting upwardly therefrom, is an angle bar 51 which extends upwardly about two-thirds the distance between the lower horizontally disposed angle bar 26 and the upper horizontally disposed angle bar 47. This angle bar 51 has spot welded thereto another vertically disposed angle bar 52 which is off-set and extends upwardly from the angle bar 51 and is welded at its upper end to the horizontally disposed angle bar 47 to thus form a single member, broadly designated at 53, between the lower horizontally disposed angle bar 26 and the upper horizontally disposed angle bar 47.

Mounted between, and welded at each end thereof to the vertically disposed angle bars 50 and 51 is a vertically disposed plate 54 which is at the same level as the plate 36 at the opposite side of the machine and also has an inwardly projecting portion 55 (Figure 5) similar to the inwardly projecting portion 37 of the plate 36. Disposed below the plate 54, intermediate the plate 54 and the angle bar 26, is a vertically disposed brace plate 57 (Figure 3) which is welded at one end to the vertically disposed angle bar 50 and at its other end to the vertically disposed angle bar 51.

Disposed below the plate 57, and welded at one end thereof to the vertically disposed angle bar 50 and at the other end thereof to the vertically disposed angle bar 51,

is a horizontally disposed bar 58. This bar 58 is at the same level as the angle bar 42 disposed at the opposite side of the machine. Disposed approximately half way between the upper angle bar 47 and the lower angle bar 26, and welded at one end to the vertically disposed angle bar 45 and at its other end to the vertically disposed angle bar 50, is a horizontally disposed angle bar 62 (Figures 3 and 5).

By referring to Figure 5, it may be observed that the angle bar 62 has, secured to the end thereof remote from the observer, by any suitable means such as screws 65, a horizontally disposed angle bar 63 which is a part of the conveyor means associated with this machine and which extends to the left in Figure 5 and has secured to the free end thereof a vertically disposed angle bar 66 which extends downwardly and is supported on the floor F (Figure 4).

Secured to the angle bar 66, by any suitable means such as screws 67, is a short angle bar 68 which has connected to the upper and lower ends thereof horizontally disposed guide bars 71 and 72. These guide bars 71 and 72 extend to the left, as observed in Figure 4, and are welded at their other ends to a vertically disposed angle bar 73 which is secured, by any suitable means such as screws 74, to a downwardly projecting angle bar 75, the upper end of which is welded to the horizontally disposed angle bar 63 and the lower end of which is supported on the floor F. The guide bars 71 and 72 have mounted for sliding movement therebetween, a bearing block 76, which has the end of a threaded shaft 77 rotatably mounted therein and which extends to the left in Figure 4 and threadably penetrates an adjustment nut 78. The adjustment nut 78 is rotatably mounted in the flange of the angle bar 73.

Disposed in spaced relation to the angle bar 63 and extending from the angle bar 62 (Figure 5), is a horizontally disposed angle bar 64 which is secured to the angle bar 62, by any suitable means such as screws 82. The angle bar 64 extends to the left in Figure 5 and has, extending downwardly from the other end thereof (Figure 1), a vertically disposed angle bar 83 which is welded at its upper end to the horizontally disposed angle bar 64 and is supported on the floor F at its lower end.

The vertically disposed angle bar 83 has secured thereto, by any suitable means such as screws 85, a vertically disposed short angle bar 86 which has, projecting horizontally from the upper and lower ends thereof, horizontally disposed guide bars 87 and 88 which are welded, at their other ends, to a vertically disposed short angle bar 90 which is secured, by any suitable means such as screws 91, to a vertically disposed angle bar 92 which is welded at its upper end to the horizontally disposed angle bar 64 and is supported at its lower end on the floor F.

Mounted for horizontal sliding movement between the guide bars 87 and 88 is a bearing block 93 which has rotatably mounted therein one end of a threaded shaft 94 which threadably penetrates a nut 95 rotatably mounted in the flange of the angle bar 90. It is thus seen that the bearing blocks 76 and 93 have horizontal adjustment relative to the vertically disposed angle bars 66 and 75 and 83 and 92, respectively, to thus take up slack in a chain conveyor 244 to be later described.

Welded to the free end of the horizontally disposed angle bar 63 is a horizontally disposed transverse angle bar 96 which extends towards the observer in Figure 5 and is welded at its other end to the end of the horizontally disposed angle bar 64, to thus hold the ends of the angle bars 63 and 64 in correct spaced relation. Disposed in spaced relation to the angle bar 62, as observed in Figure 5, is an angle bar 97 which is connected at one end to the horizontally disposed angle bar 63 and at its other end to the horizontally disposed angle bar 64.

Disposed between the angle bars 63 and 64 and connected at one end to the angle bar 62 and at its other end to the angle bar 97, by any suitable means such as

welding, is an angle bar 100 (Figures 5 and 8). The angle bars 62, 63, 64 and 96 and associated parts comprise a framework for the conveying means associated with this machine.

Mounted on the upper surfaces of the I-beams 21 and 22 is a transverse angle bar 105 which is also welded to the vertically disposed angle bars 27 and 45. The upper ends of these angle bars 27 and 45 are connected by a horizontally disposed angle bar 106 which is welded at each end to the angle bars 27 and 45. Disposed intermediate the ends of the angle bars 27 and 45, and being welded thereto, is a horizontally disposed angle bar 107 (Figures 1 and 62).

Disposed approximately half-way between the angle bar 107 and the bottom angle bar 105, is a horizontally disposed angle bar 108 which is welded at one end to the vertically disposed angle bar 27 and at its other end to the vertically disposed angle bar 45. Mounted on the upper surface of the angle bar 44, as observed in Figure 2, is a transverse horizontally disposed channel bar 110 which is secured thereto, by any suitable means such as welding. This channel bar 110 extends across the framework 20 and is mounted at its other end on the upper surface of a horizontally disposed angle bar 111 which is welded at its right-hand end, as observed in Figure 3, to the vertically disposed angle bar 45 and at its left-hand end in Figure 3 to the vertically disposed angle bar 50.

By referring to Figures 4 and 62 it may be observed that the lower end of the vertically disposed angle bars 28 and 46 are joined together by a horizontally disposed angle bar 115 which is welded at each end to the vertically disposed angle bars 28 and 46 and is also welded to the top surfaces of the I-beams 21 and 22. The upper ends of the angle bars 28 and 46 are connected by a horizontally disposed channel bar 116 which has disposed therebelow, in parallel relation thereto, a horizontally disposed channel bar 117 and disposed below the horizontally disposed channel bar 117, in spaced relation thereto, is another horizontally disposed channel bar 118 and the channel bars 116, 117 and 118 are all welded at one end to the vertically disposed angle bar 28 and they are all welded at their other ends to the vertically disposed angle bar 46.

Welded adjacent the upper ends of the angle bars 34 and 52, and spanning the distance therebetween, is a horizontally disposed angle bar 119 (Figures 5 and 62). Welded adjacent the upper ends of the angle bars 33 and 50, and spanning the distance therebetween, is a horizontally disposed channel bar 120.

Extending longitudinally of the machine and mounted in spaced relation to the horizontally disposed angle bars 31 and 47 are spaced channel bars 122 and 123 which are secured, by any suitable means such as welding, on the upper surface of the channel bar 116 at one end and on the upper surface of the channel bar 120 at the other end and on the upper surface of the angle bar 119 intermediate their ends.

It may be observed in Figures 4 and 62 that there is disposed between, and welded to, the vertically disposed angle bars 34 and 52, a horizontally disposed channel bar 124. Welded at one end to the horizontally disposed channel bar 117 and disposed intermediate the ends of the channel bar 117 is a forwardly projecting channel bar 125 which is welded at its forward end to the transverse channel bar 124. Disposed in spaced relation to the channel bars 35 and 125 is another channel bar 126, which is also welded at one end to the channel bar 117 and is welded at its forward end to the channel bar 124. The upper surfaces of the channel bars 125 and 126 are at the same level as the upper surface of the channel bar 35 (Figure 4).

Disposed immediately below the channel bar 120 in superposed relation thereto and being welded to the vertically disposed angle bars 33 and 50, is a horizontally

disposed channel bar 127. This channel bar 127 has, welded thereto and extending rearwardly therefrom, spaced channel bars 628 and 629 which are welded adjacent their rear ends on the upper surface of the channel bar 124.

Welded on the front vertical surfaces of the horizontally disposed channel bars 117 and 118, at the rear of the machine, are spaced vertically disposed channel bars 132 and 133 (Figures 2, 3, 4 and 62). Welded to the rear surfaces of the vertically disposed angle bars 34 and 51, and spanning the distance therebetween, are spaced horizontally disposed angle bars 135, 136 and 139 (Figures 2 and 3). The angle bar 135 extends outwardly beyond the vertically disposed angle bar 34 and has welded thereto a horizontally disposed angle bar 137 which extends rearwardly and is welded at its other end to the vertically disposed angle bar 28. Welded to the opposite end of the angle bar 135 is a rearwardly projecting angle bar 138 which is welded at its other end to the upper surface of a horizontally disposed transverse angle bar 140 (Figure 4). The angle bar 140 is welded at each end to the vertically disposed angle bars 28 and 46. An angle bar 141 is welded at each end to the vertically disposed angle bars 28 and 46 and is disposed at the same level as the angle bar 136 and these angle bars 136 and 141 have longitudinally extending spaced bars 142 and 143 (Figure 4) which are secured to the angle bars 136 and 141, by any suitable means such as welding.

Welded to the lower ends of the vertically disposed angle bars 33 and 50 (Figures 41 and 42) is a lower angle bar 144 which is also mounted on the angle bars 25 and 26. By referring to Figure 41 it may be observed that there is disposed above the angle bar 144, and in spaced relation thereto, a horizontally disposed angle bar 147 which is welded at one end to the vertically disposed angle bar 33 and at its other end to the vertically disposed angle bar 50.

There is disposed above the angle bar 147, and in spaced relation thereto, a horizontally disposed angle bar 150 which is welded at one end to the vertically disposed angle bar 33 and at its other end to the vertically disposed angle bar 50. There is disposed above the angle bar 150 and in spaced relation thereto another angle bar 151 one end of which is welded to the vertically disposed angle bar 33 and the other end of which is welded to the vertically disposed angle bar 50. Extending forwardly from, and welded to, the horizontally disposed angle bar 151 are horizontally disposed bars 152 and 153 (Figures 2, 3 and 41). These horizontally disposed bars 152 and 153 extend to the front end of the machine and are welded at their front ends to the horizontally disposed transverse angle bar 107. The angle bars 144, 147, 150 and 151 are omitted from Figure 62 for purposes of clarity.

Welded to the rearmost vertical surface of the horizontally disposed channel bar 110 are vertically disposed angle bars 157 and 158 (Figures 2, 3, 5 and 62). Welded against the proximate surfaces of the angle bars 157 and 158, and also welded onto the horizontally disposed channel bar 110 and the horizontally disposed angle bar 108 are horizontally disposed and longitudinally extending angle bars 160 and 162.

Welded to the top surface of the horizontally disposed I-beam 21 is one end of transversely disposed channel bars 165 and 166 which extend across the machine and are welded at their other ends on the top surface of the horizontally disposed I-beam 22 (Figures 5, 54 and 55). These channel bars 165 and 166 are disposed substantially below the channel bar 110 heretofore described.

The parts heretofore described comprise the frame 20 of this machine and, for purposes of clarity, any bearings or other associated parts to the machine, have been omitted from the specification thus far.

There is disposed adjacent the rear end of the machine, as observed in Figure 5, a framework, broadly designated at 170, on which is mounted the driving means for this

machine. The framework 170 is clearly shown in Figures 1, 3-A, 4 and 5 and comprises vertical angle bars 171 and 172, at the front side thereof, as observed in Figure 1, and the angle bar 172 has welded to the upper end thereof an angle bar 173 which extends to the left in Figure 1 and is welded to the angle bar 171.

The angle bar 172 also has extending rearwardly therefrom, and welded to the upper end thereof, a channel bar 174 which is welded at its other end to a vertically disposed angle bar 175 (Figure 3-A) which extends downwardly and is supported on the floor F. The upper end of the angle bar 175 also has welded thereto a horizontally disposed angle bar 176 which extends to the left in Figure 5 and is welded at its other ends to a transverse angle bar 177, one end of which is welded to the vertically disposed angle bar 171 and the other end of which is welded to a vertically disposed angle bar 180.

The angle bar 180 also has welded to the upper end thereof a horizontally disposed angle bar 181 which extends to the right in Figure 5 and is welded at its other end to the upper end of a vertically disposed angle bar 182. The angle bar 182 extends downwardly and is supported on the floor F and intermediate the ends of the angle bar 182 there is welded thereto a horizontally disposed bar 183 (Figure 3-A) which passes by and is welded to the vertically disposed angle bar 175 and is welded at its other end intermediate the ends of the vertically disposed angle bar 172 (Figure 3-A).

Welded at one end on the upper surface of the horizontally disposed angle bar 173 is a transverse channel bar 184 (Figure 1) which is in spaced relation to the channel bar 174 and is welded at its other end on the upper surface of the horizontally disposed angle bar 176. Mounted on the upper surfaces of the angle bars 173 and 176, and spanning the distance therebetween, is an electric motor 10 having electric wires 11 and 12 extending therefrom to an electrically operated magnetic switch 13 disposed on the upper end of the vertically disposed angle member 171 (Figures 1, 4 and 5). This magnetic switch 13 is of a type such as is manufactured by the Federal Electric Products Company, Inc. and is illustrated on page 4, section 3b/4 of Sweet's File for product designers, 1946 issue.

Extending from the magnetic switch 13 are electric wires 15 and 16 which extend to the frame 20 and are connected to a manually operated switch 17 mounted on the vertically disposed angle bar 45. Extending from the other side of the switch 17 are electric wires 18 and 19 which are connected to a suitable source of electrical energy, not shown.

The motor 10 has extending therefrom, a shaft 190 which has fixedly mounted thereon a pulley 191 (Figure 5) on which is mounted one end of a flat belt 192 which extends to the right in Figure 5 and is mounted on a larger pulley 193. The pulley 193 is disposed between the horizontally disposed angle bars 176 and 181 and is fixedly mounted on a shaft 194, one end of which is rotatably mounted in a bearing block 195 fixedly secured on the horizontally disposed angle bar 181 by any suitable means such as screws 196.

The shaft 194 is mounted at its other end in a suitable gear reduction unit which is mounted on the transverse channel bars 174 and 184 and is secured thereto, by any suitable means such as screws 200. The shaft 194, which enters the gear reduction unit, transmits rotation to a transverse shaft 203 which also extends out of the gear reduction unit.

This shaft 203 has fixedly mounted thereon a sprocket wheel 204 on which a double sprocket chain 205 is mounted. The double sprocket chain 205 extends forwardly and downwardly and is mounted on a sprocket wheel 207 which is fixedly mounted on a transverse shaft 208 (Figures 1, 2 and 4).

The shaft 208 extends across the frame 20 and is rotatably mounted in bearing blocks 210 which are

secured, by any suitable means such as screws 211, on the horizontally disposed angle bars 111 and 44 (Figure 4). The shaft 208 has fixedly mounted on the right-hand end thereof, as observed in Figure 1, a double sprocket wheel 212 having a double sprocket chain 213 mounted thereon which extends upwardly and is mounted on a sprocket wheel 214 to be later described.

Disposed between the bearing blocks 210, at the right-hand end of the shaft 208, as observed in Figure 1, are miter gears 215 and 216 which are spaced apart from each other and are fixedly mounted on the shaft 208 (Figures 41 and 42). The miter gear 215 engages a miter gear 217 which is fixedly mounted on one end of a shaft 218 which extends towards the front of the machine, or to the left, as observed in Figure 41, and is rotatably mounted in bearing blocks 219 and 220 fixedly secured on bars 223 and 224, respectively, by any suitable means such as screws 225. The bars 223 and 224 are welded to the upper surface of the angle bar 44 and extend inwardly therefrom and at their innermost ends they are welded to angularly disposed bars 226 which extend downwardly and to the right in Figure 1 and are welded at their lower ends to the angle bar 25.

Fixedly mounted on the shaft 218 between the bearing blocks 219 and 220 is a sprocket wheel 227 which has mounted thereon a sprocket chain 230 which extends upwardly and is mounted on a sprocket wheel 231 fixedly mounted on a shaft 232 (Figures 1, 41 and 42). The shaft 232 is rotatably mounted at its forward end in a bearing block 235 (Figure 41) which is secured, by any suitable means such as bolts 236 (Figure 2), to the vertically disposed angle bar 32.

The shaft 232 is rotatably mounted at its rear end, in a bearing block 237 (Figures 41 and 42) which is secured, by any suitable means such as bolts 238, on the transverse angle bar 151. Fixedly mounted on the shaft 232 are sprocket wheels 240 and 241 of a chain conveyor, broadly designated at 243 (Figures 2, 41 and 42).

The sprocket wheels 240 and 241 have mounted thereon sprocket chains 244 and 245, respectively. These sprocket chains 244 and 245 extend to the left in Figures 1, 5 and 42 and are mounted at their other ends on sprocket wheels 246 and 247, respectively (Figures 1 and 4), which are fixedly mounted on a shaft 248 rotatably mounted in the bearing blocks 76 and 93 heretofore described and which may be taken up as stated so as to provide tension, as desired, in the sprocket chains 244 and 245.

By referring to Figures 9 to 12 inclusive it may be observed that every seventh link of the chains 244 and 245 has out-turned ears 249 integral therewith to which channel-shaped trays 250 are secured, by any suitable means such as bolts 255, and these trays 250 each span the distance between the sprocket chains 244 and 245 and extend beyond the same at both ends. The trays 250 are channel-shaped and each end of them is open. Mounted on the front end of each of the trays 250 and secured thereto, by any suitable means such as welding, is an angle clip 256 which is rolled over at its upper end to form a lip 257.

It will be noted that the upper edges of the channel-shaped trays 250 are each rolled inwardly to form a lip 258 and that one of the flanges of each of the channel-shaped trays are bent outwardly as at 259 for purposes to be later described.

Secured to the angle bars 64 and 100 (Figure 5), by any suitable means such as screws 265, are bearing blocks 266 in which is rotatably mounted, a shaft 267. This shaft 267 (Figure 5) has fixedly mounted thereon, a pulley 268 on which one end of a conveyor belt 270, of a belt conveyor broadly designated at 260 is mounted. This conveyor belt 270 passes over and around the pulley 268 and its lower surface then engages a take-up roll

271 (Figures 6, 7 and 8) fixedly mounted on a shaft 272 which is rotatably mounted in bearing blocks 273 secured, by any suitable means such as screws 274, to the upper surfaces of the angle bars 64 and 100.

The lower reach of the conveyor belt 270 then passes into a box-like structure 275 which extends longitudinally of the conveyor 260 to thus serve as a housing for the lower reach of the conveyor belt 270 as well as a support for the upper reach of the conveyor belt 270. The conveyor belt 270 extends to another pulley, not shown, which is mounted and driven in a conventional manner and is part of a conventional conveyor and a further description is not deemed necessary. However it is evident that this belt conveyor 260 would extend as far as desired beyond the intake end of the chain conveyor belt 243, sometimes extending even into another room for conveying articles to be transferred to the chain conveyor trays.

It may be observed in Figures 41 and 42 that the miter gear 216, which is fixedly mounted on the transverse shaft 208, engages a miter gear 280 which is fixedly mounted on a shaft 281 disposed longitudinally of the machine. The shaft 281 is rotatably mounted in bearing blocks 282 and 283 (Figure 41).

The bearing block 282 is secured on the upper surfaces of the transverse angle bar 147, by any suitable means such as screws 284, and the bearing block 283 is fixedly mounted on the lower surface of a transverse angle bar 285, by any suitable means such as screws 286. The transverse angle bar 285 is welded at one end to the upper surface of the bar 58 (Figure 3) and at its other end to the upper surface of the angle bar 42 (Figures 2 and 62).

Fixedly mounted on the shaft 281 and disposed between the bearing blocks 282 and 283, is a Geneva motion driving member 290 having a hub portion integral therewith which is convex on one side of the periphery, as at 291, and is concave at the opposite side of the periphery, as at 292 (Figures 41 to 44 inclusive). The driving member 290 has, integral therewith, an outwardly projecting portion 293 which is slidably penetrated by a shoulder screw 294 (Figure 45) having a roller 295 rotatably mounted thereon and said shoulder screw 294 being confined in the portion 293 by a lock nut 296. This roller 295 is adapted to intermittently engage radially spaced grooves 297, one at a time, in the periphery of a star-wheel 298. The star wheel 298 has concave surfaces 299 between each of the radially spaced slots 297 which are intermittently engaged by that portion of the Geneva motion driving member which is opposite from the roller 295.

The concave surfaces 299 have the same curvature as the convex surface of driver 290 and therefore agree with the arcuity of the convex surface 291 to thus cause the convex surface 291 to cooperate with the concave surfaces 299 one at a time, to serve as a locking means for the Geneva stop mechanism.

The star wheel 298 is fixedly mounted on the shaft 300 (Figures 42, 43 and 44) which is rotatably mounted in bearing blocks 301 and 302. The bearing block 301 is fixedly mounted on the upper surface of the transverse angle bar 147, by a suitable means such as screws 304, and the bearing block 302 is secured on the lower surface of the angle bar 285, immediately behind bearing block 283 in Figure 41, by any suitable means such as screws 305.

Also fixedly mounted on the shaft 300 is a gear wheel 306 engages, and drives, a pinion 307 fixedly mounted on a shaft 310 (Figures 41 to 44 inclusive). The shaft 310 is rotatably mounted in bearing blocks 311 and 312 (Figure 61). The bearing block 311 is secured on the upper surface of the transversely disposed angle bar 150, by any suitable means such as screws 314, and the bearing block 312 is secured on the lower surface of the

transverse angle bar 139, by any suitable means such as screws 315 (Figure 61).

Engaging the right-hand vertical surface of the pinion 307, as observed in Figure 41, is a sleeve 316 which extends to the right and, as may be observed in Figure 56, the other end of the sleeve 316 engages a hub portion 317 of a turret, broadly designated at 320. This turret 320 may be of a single casting or it may be built up of several different parts. In this instance, the turret 320 is shown in the drawings as being of two halves 321 and 322 (Figure 47) which, after they are cast, may be secured together, by any suitable means such as welding or the like. The turret 320 is fixedly mounted on the shaft 310 (Figure 46) and intermittent partial rotation is thus transmitted to the same through the pinion 307 which is also fixedly mounted on the shaft 310.

The turret 320 is, in this instance, shown to be substantially square and has each corner of the same cut away so that rotation of the turret 320 will not cause the corners to project outwardly beyond the frame 20. It may be observed in Figures 47 and 61 that the turret 320 is cored as at 324 and has secured to each side thereof metal plates 325 and 326, by any suitable means such as by spot welding. For purposes of later description the turret has edges 327, 328, 329 and 330. Penetrating the turret 320 and also penetrating the plates 325 and 326, and being in spaced relation to the edges 327 to 330 inclusive, are spaced bores 332, there being four of them disposed adjacent each of the sides 327 to 330 inclusive.

Mounted between the Geneva motion driving member 290 and the bearing block 283 (Figure 41), is a sprocket wheel 335 which is fixedly mounted on the shaft 281. The sprocket wheel 335 has mounted thereon, one end of a sprocket chain 336 which extends to the right, in Figure 46 and is mounted at its other end on a sprocket wheel 337. The sprocket wheel 337 is fixedly mounted on a shaft 338 rotatably mounted in bearing blocks 340 and 341 (Figure 2). The bearing block 340 is secured to the horizontally disposed angle bar 44 as well as the vertically disposed angle bar 33 and the bearing block 341 is secured to the vertically disposed angle 34, both of the bearing blocks being secured, by any suitable means such as screws 342 and 343, respectively.

The shaft 338 also has fixedly mounted thereon, a cam wheel 345 (Figures 2, 48 and 49) having a lobe portion 346 integral therewith and the cam wheel 345 is secured to the shaft 338, by any suitable means such as a set screw 347. The lobe 346 of the cam wheel 345 is adapted to intermittently engage a horizontally disposed plunger 350 which is mounted for horizontal sliding movement in a valve housing 351 (Figures 47, 48 and 49) which is secured on an angle clip 352, by any suitable means such as screws 353. The angle clip 352 is welded to the horizontally disposed angle bar 25.

The valve housing 351 has a partition 354 extending thereacross which has a port 355 therethrough which is intermittently closed by a valve collar 356 fixedly mounted adjacent the other end of the plunger 350. The valve housing 351 has chambers 357 and 358 therein which are formed by the partition 354 disposed within the housing 351. Projecting to the left, in Figure 49, from the chamber 357, and disposed in the housing 351, is a bore 360 in which one end of a compression spring 361 is mounted and the other end of which engages one side of the valve collar 356 to thus urge the plunger 350 outwardly against the peripheral surface of the cam wheel 345.

Threadably mounted in one end of the housing 351, transversely of the plunger 350, is a union 362, the other end of which is threadably connected to one end of an elbow 363 (Figure 47) and the other end of the elbow 363 has, threadably mounted therein, one end of a pipe 364 which extends from a suitable source of compressed air, such as compressed air tank 368 (Figure 4). Thus, the compressed air will enter the chamber 357 through

the pipe 364 and when the lobe 346 of the cam wheel 345 engages the plunger 350, valve 356 will be opened and compressed air will pass into the chamber 358. Threadably mounted in that end of the housing 351 which is opposite the nipple 362, is one end of a hollow fitting 365 the other end of which is connected to a flexible hose 366 (Figures 39, 40 and 47 to 49 inclusive). The flexible hose 366 extends upwardly in Figures 39, 40, 46 and 47 and is connected by means of one or more reducing plugs 367 to an elbow 370 which is threadably connected at its other end to a vertically disposed pipe 371.

It may be observed in Figure 47 that the pipe 371 has extending rearwardly therefrom, with respect to the front of the machine, horizontally disposed nipples 373 which are secured to the pipe 371, by any suitable means such as welding, and are in alinement with spaced bores 374 in the left-hand side of the pipe 371, as observed in Figure 47. The upper end of the pipe 371 has threadably mounted thereon, a pipe elbow 375, the other end of which is connected to a nipple 376 having a smaller nipple 377 extending therefrom which is identical to the nipples 373 heretofore described. The nipple 376 is horizontally disposed and is secured to a horizontally disposed channel bar 380 by a U-shaped clamp 381 secured to the upper surface of the channel bar 380, by any suitable means such as bolts 382 (Figure 47).

The channel bar 380 is welded at one end to the vertically disposed plate 40, extends across the frame 20, and is welded at its other end to the vertically disposed plate 57.

The sprocket chain 336, (Figure 46) also engages a sprocket wheel 383 fixedly mounted on a shaft 384 which is disposed longitudinally of the machine. The shaft 384 is rotatably mounted in bearing blocks 385 and 386 (Figures 46 and 61), the bearing block 385 being secured to the vertically disposed bar 43, by any suitable means such as screws 387, and the bearing block 386 being secured to the vertically disposed angle bar 34, by any suitable means such as screws 390.

The shaft 384 has fixedly mounted thereon a flanged pulley 391 on which one end of an endless conveyor belt 392 is mounted. The conveyor belt 392 extends across the frame 20 and is mounted at its other end on a flanged pulley 393 fixedly mounted on a shaft 394. One end of the shaft 394 is rotatably mounted in a bearing block 395 (Figures 56 and 61) which is secured, by any suitable means such as screws 396, to the vertically disposed angle bar 51. The combined weight of the conveyor belt 392 and the flanged pulley 393 being very light, it is not necessary to support the other end of the shaft 394.

The lower surface of the upper reach of the conveyor belt 392 rides on a sheet metal plate 397 which has an upwardly extending portion 398 (Figures 59 and 60), at one side of the conveyor belt 392, and also has an angularly disposed portion 400 which projects upwardly from the other side of the conveyor belt 392 and its uppermost edge is disposed adjacent the lower edge of the turret 320. The two ends of the portion 400 of the sheet metal member 397, are secured, by any suitable means such as screws 401, to sheet metal brackets 402 which extend outwardly from each end of the portion 400 and the remote ends of the brackets 402 are secured by any suitable means such as screws 403 to the vertically disposed angle bars 34 and 51.

The purpose of the above described arrangement is to permit the compressed packages, to be later described, when ejected to fall down the sloping portion 400 and to roll onto the endless belt 392 to be delivered to a suitable location.

Disposed at the left-hand end of the conveyor belt 392, as observed in Figures 58 and 61, is a chute 405 which projects outwardly and downwardly and has a cup portion 406 into which articles roll by gravity after they have left the end of the conveyor belt 392 in a manner to be later described. The cup portion 406 of the chute

405 is welded at its right-hand surface, as observed in Figure 58, to the left-hand vertical surface of the horizontally disposed angle bar 25.

Welded to the front vertical surface of the angle bar 136 (Figures 53 and 56) is a horizontally disposed angle bar 410 which is also welded, at each end, to the vertically disposed angle bars 34 and 51. This horizontally disposed angle bar 410 also has welded, on the upper surface thereof, a horizontally disposed bar 411 (Figures 52, 53, 56 and 61) which is rectangular in cross-section and has secured to the upper surface thereof, by any suitable means such as screws 412, a plurality of nests 413 there being four nests, in this instance, to cooperate with the bores 332 disposed adjacent each of the four edges of the turret 320. Fitted on each of the nests 413, and projecting upwardly therefrom, are sheet metal chutes 417 which are rectangular in cross-section and are partially open at one side as indicated at 418 (Figures 50 and 52). The nests 413 each have a V-shaped groove 420 at their upper ends and that portion of the chute 417 that is fitted on each of the nests 420 has disposed at its forward and rearward ends thereof, adjacent the V-shaped groove 420, circular coinciding openings 421 (Figures 52 and 61) which are adapted to accommodate ingress and egress of a back-up plunger to be later described.

The chutes 417 extend upwardly and each of them have, welded integral therewith, angularly disposed chutes 425 which are of the same dimensions in cross-section as the vertically disposed chutes 417 and these chutes 425 are disposed in superposed relation to each other. The upper ends of the chutes 425, as observed in Figures 50 and 51, are welded to an elongated tray 430 which is angularly disposed but is not disposed at as steep an angle as the angularly disposed chutes 425. The elongated tray 430 is open at its upper end at 431 and is closed at its lower end as at 432 and has a plurality of rectangular openings 434 in the lower surface thereof each of which is in alinement with the uppermost ends 40 of each of the angularly disposed chutes 425.

The elongated tray 430 is adapted to receive empty tubular containers 435 (Figure 63) which roll along the elongated tray 430 and fall by gravity through the openings 434 into the chutes 425. That portion of the tray 430 which is displaced by the cutting of the openings 434 in the lower surface of the elongated tray 430, is bent downwardly as at 436 to thus form a smooth surface for ingress of the tubular containers 435 into the chutes 425. The tubular containers 435 are of a length equivalent to the inside width of the elongated tray 430, as well as the width of the chutes 425 and 417, and the diameter of the tubular containers 435 is equivalent to the inside height of the chutes 425 and 417. The tubular containers 435 have their opposite ends crimped, as at 435a so that they are thereby guided through the various operations of this machine more efficiently. The crimping of the ends of the tubular containers 435, of course, causes their ends less likely to hang while traveling through the various chutes above described. However, the primary purpose of crimping the ends of these containers is to cause this crimping to temporarily bulge outwardly when a compressed article is forced into the containers and these crimped ends will hold the compressed article within the confines of the tubular containers after they are ejected from the turret and until suitable disks, not shown, are then inserted into the ends of the tubular containers to not only assist in retaining the compressed article, within the container, but also to protect the ends of the compressed article from foreign matter.

The chutes 425 are secured in superposed relation to each other by a strap iron clamp member 437, the two ends of which are secured to each other by a bolt 438. The chutes 425 are secured to the vertically disposed angle bar 52 (Figures 3 and 4) by a U-bolt 439 which engages

all of the chutes 425 and the upper reach of the U-bolt 439 extends across the top of the chutes 425 while the lower reach of the U-bolt 439 extends across the lower surface of the bottom chute 425 and this U-bolt is secured, by any suitable means such as nuts 440, to a vertically disposed short angle bar 441 welded to the vertically disposed angle bar 52. The lowermost chute 425 is also supported on the upper end of the vertically disposed angle bar 51. It has heretofore been stated how the lowermost ends of the chutes 425 are integral with the vertically disposed chutes 417 and the lower ends of the chutes 417 are fitted over the upper ends of the nests 413 to thus complete the support for the chutes 425.

The tubular containers 435 enter the upper ends of the chutes 425 and will roll by gravity down the chutes 425, into the chutes 417 and the lowermost of the tubular containers 435, in each of the chutes 417, will come to rest in the V-shaped groove 420 in the upper end of each of the nests 413 and as each tubular container is moved out of the V-shaped groove 420, in a manner to be later described, the next succeeding tubular container 435 will, of course, fall by gravity into the V-shaped groove 420, inasmuch as the tubular containers 435 will be disposed in superposed relation to each other as they are fed into the chutes 425 and 417.

The chutes 425 and 417 are filled with the containers 435 successively, that is, the chute 425 furthest to the right, in Figure 51, will be filled completely and then the next chute 425 to the left, in Figure 51, will be filled and so on until all the chutes 425 are filled.

In the operation of this machine, articles A, such as sanitary napkins are placed on the intake end, not shown, of the conveyor belt 270 of the conveyor 260 as they are removed from other machines in which they have formerly been processed. These articles A pass along the conveyor belt 270 and as they pass adjacent the chain conveyor 243, they are taken off the conveyor belt 270 of the conveyor 260 by operators and placed on the channel shaped trays 250 so that one end of the article is disposed at the open end of the channel shaped member 250 and the other end of the article is disposed against the angle clip 256 and so that this end of the article A is disposed beneath the lip 257, of the angle clip 256, to thus assist in confining the article A on each of the channel shaped trays 250.

Now, there is fixedly mounted on the shaft 208, and disposed between the sprocket wheel 207 and the miter gear 215, a sprocket wheel 450 (Figure 41) which has mounted thereon a sprocket chain 451 the other end of which is mounted on a sprocket wheel 452 fixedly mounted on a shaft 453 disposed crosswise of the machine (Figures 3, 13, 14 and 41). The shaft 453 is rotatably mounted in bearing blocks 454 and 455. The bearing block 454 is secured, by any suitable means such as screws 456, to the upper surface of the horizontally disposed angle bar 111 (Figure 3). The bearing block 455 is secured, by any suitable means such as screws 456, to a block 458 the lower end of which is welded to the upper surfaces of horizontally disposed channel bars 461 and 462 (Figures 54 and 55) which are welded at one of their ends to the horizontally disposed I-beam 21 and are welded at their opposite ends to the horizontally disposed I-beam 22.

Fixedly mounted on the shaft 453 is a closed cam wheel 463 (Figures 13 and 14) having a continuous groove 464 in one side thereof which is engaged by a cam follower 465 projecting from a bell crank 467. The bell crank 467 extends to the left in Figure 13 and has, integral therewith, a bearing portion 468 which is fixedly mounted on a shaft 471. The shaft 471 is rotatably mounted in bearing blocks 472 which are secured, by any suitable means such as screws 473, to the horizontally disposed angle bars 160 and 162 (Figure 5). The bell crank 467 also projects upwardly and is pivotally connected, as at 474, to a forked member 475 which

has, threadably mounted in the upper end thereof, a connecting rod 476 which is secured to the forked member 475 by a lock nut 477.

The connecting rod 476 extends upwardly in Figure 5 and threadably penetrates a forked member 480 and is secured therein by a lock nut 481. The upper end of the forked member 480 has pivotally secured thereto, as at 482, an arm 483 the opposite end of which is fixedly mounted on a shaft 485 (Figure 5). Also fixedly mounted on the shaft 485, in spaced relation to the arm 483, is the upper end of a lever bar 487 which projects downwardly and has a bearing portion 490 at its lower end which has, oscillatably mounted therein, a stub shaft 491 (Figures 13, 14, 20 and 21). Fixedly mounted on the shaft 491, and disposed at each side of the bearing portion 490 of the lever 487, are collars 493 and 494. The collars 493 and 494 are welded, as at 495, to a substantially horizontally disposed plate 496 which extends crosswise of the machine and has welded at each end thereof substantially horizontally disposed bars 497.

Each of the bars 497 has, mounted on its outer end, a stud 498 having a roller 500 rotatably mounted thereon. The roller 500 is adapted to engage the upper surface 501 of a block 502 and associated parts, there being a block 502 at each side of the machine, as observed in Figure 13, which is secured to a vertically disposed and longitudinally extending plate 503, by any suitable means such as screws 504 (Figures 17 and 18). In the operation of this machine, the roller 500 traverses, not only the upper surface of the plate 502, but the upper surface of a bar 505 which is also secured to the vertically disposed plate 503, by a suitable means such as screws 506. The roller 500 is confined from moving upwardly, away from engagement with the upper surface of the bar 505, by a horizontally disposed bar 508, which is secured to the longitudinally extending plate 503, by any suitable means such as screws 509.

When the roller 500 has moved from the position shown in Figure 13 to the position shown in Figure 14, it will engage an angularly disposed finger 510 which is pivotally mounted, as at 512, on the end of the horizontally disposed bar 508. As the roller 500 moves from the position shown in Figure 14 to the position shown in Figure 15, it engages the lower surface of the finger 510 causing it to move from the position shown in Figures 13 and 14 to the position shown in Figure 15.

The fingers 510 have, extending from the remote surfaces thereof, pins 511 which extend through arcuate slots 515 in the plates 503 and have, mounted on their remote ends, one end of tension springs 516. The tension springs 516 extend downwardly and forwardly, at an angle, and are mounted at their lower ends on spring perches 517 (Figure 19), there being one of these spring perches 517 on the remote surface of each of the plates 503. It may be observed in Figure 3 that the plate 503, which is disposed on the left-hand side of the machine, is secured, at its rear end, to an angle clip 518, by any suitable means such as screws 519, and this angle clip 518 is secured, by any suitable means such as screws 521, to the vertically disposed angle bar 50 of the frame 20. The front end of this plate 503, as observed in Figure 3, is secured, by any suitable means such as bolts 522, to the upper end of a vertically disposed angle bar 523 which extends downwardly and the lower end of which is welded to the horizontally disposed angle bar 62.

The other horizontally disposed plate 503, at the right-hand side of the machine, is secured at its left-hand or front end, as observed in Figure 2, to the vertically disposed angle bar 32, by any suitable means such as screws 524, and the other end of this plate 503 is secured to an angle clip 525, by any suitable means such as screws 526, and this angle clip 525 is in turn secured to the vertically disposed angle bar 33, by any suitable means.

Now, in the operation of this machine, as the rollers

500 move along the upper surface of the horizontally disposed bars 505, they will raise the fingers 510 to the position shown in Figure 15 and will then move beyond the end of the fingers 510 so that the free ends of the fingers 510 will be urged downwardly to their original position by the tension springs 516. Then, as the rollers 500 move to their original position, as shown in Figure 13, the rollers 500 engage the upper surfaces of the fingers 510, as well as the upper surfaces of the horizontally disposed bars 508. The horizontally disposed bars 508 each have an angularly cut portion 530 at their forward ends so that, as the rollers 500 return to the position shown in Figure 13 they tend to move downwardly to thus engage the upper surfaces 501 of the blocks 502.

The above description of one of the blocks 502, which is shown in detail in Figures 17, 18 and 19, as well as in other figures, equally applies to the similar block on the other end of the mechanism. By referring to Figure 20 it will be seen that the above description will apply to the left-hand block, whereas, the right-hand block is identical and like reference characters will apply except that the right-hand block 502 and associated parts is opposite hand to the left-hand block in Figure 20.

Welded to the lower surface of the plate 496 and extending outwardly therefrom, are a plurality of spaced injector clips 531. These clips have their ends turned downwardly, as at 532, and these clips 531 are so spaced on the plate 496 so that, as the chain conveyor 243 passes a predetermined point relative to the plate 496, there will be disposed adjacent the end of each of a group of four of the trays 250 a pair of these clips 531. As the clips 531 are moved towards the chain conveyor 243 by the cam 463, two of these clips 531 will pass into the channel shaped tray 250 and the clips 531, being spaced apart from each other, will also straddle the angle clip 256 which is mounted in the tray 250.

Due to the fact that the conveyor chains move continuously, the out-turned portions 259 are provided on each of the trays 250, to facilitate ingress of the injector clips 531 as heretofore described.

As the injector clips 531 move from the position shown in Figure 13 to the position shown in Figures 14 and 15 to and beyond the position shown in Figure 16, the down-turned portions of the injector clips 531 are adapted to engage the ends of the articles A to thus move the articles A onto the upper surfaces of a plurality of folding and forming dies 535, there being one of these dies disposed in alignment with each of the articles A as they are slid off of the trays 250.

These dies 535 are part of a folding and forming unit broadly designated at 536 (Figures 22 to 30 inclusive). In this instance, there are four of the forming and foldings dies 535 shown in the drawings which are adapted to cooperate with any four of the bores 332, disposed adjacent the four edges of the turret 320. These dies 535 are secured on a supporting plate 540, by any suitable means such as screws 541. This supporting plate 540 is disposed crosswise of the machine and has, integral with each end thereof, a bearing portion 544.

Slidably penetrating the bearing portions 544, at each end of the supporting plate 540, are restricted portions 545 of vertically disposed guide posts 546. The supporting plate 540 is secured on the restricted portions 545 of the guide posts 546 by nuts 547 which are threadably mounted on the lower ends of the restricted portions 545 and are tightened against the lower surface of the plate 540.

These vertically disposed guide posts 546 slidably penetrate bearing portions 555 at remote ends of spaced horizontally disposed plates 556 (Figures 26, 29 and 30), which have welded to their upper surfaces vertically disposed plates 557 and 558 which extend crosswise of the machine and are disposed adjacent the front and rear surfaces of the plates 556.

The plates 556 have horizontal plates 559 disposed adjacent the proximate edges thereof and in spaced rela-

tion to the same. The plates 559 have disposed between the proximate edges thereof and in spaced relation thereto, a horizontal plate 561. The plates 559 and 561 are welded to the lower edges of the vertically disposed plates 557 and 558. The plates 556, 559 and 561, being spaced apart from each other, form slots 567 therebetween.

Mounted on the lower surfaces of the horizontally disposed plates 556, 559 and 561, each side of the slots 567, and being disposed longitudinally of the machine, is a plurality of angle bars 560, there being two of these angle bars disposed above each of the four dies 535.

Secured to the proximate surfaces of each pair of the angle bars 560, by any suitable means such as screws 562, are vertically disposed spaced forming plates 563. These forming plates 563 are beveled at their lower ends, as at 564, so that each pair of the plates 563 forms an inverted V-shaped groove in the bottom end thereof for purposes to be later described.

Each of the slots 567 is adapted to permit vertical sliding movement of vertically disposed folding plates 568 therein and each of these folding plates 568 also have vertical sliding movement between each pair of the plates 563. Each of these plates 568 extends upwardly through the slot 567 and is secured between longitudinally extending horizontally disposed bars 572, by any suitable means such as screws 573 (Figures 22 to 29 inclusive). These bars 572 are welded at their upper edges to horizontally disposed plates 575 which are secured to the lower surface of a horizontally, and transversely, disposed plate 576, by any suitable means such as screws 577. The horizontally disposed plate 576 is of similar shape to the plate 540 and has, integral with each end thereof, bearing portions 580 which are adapted to have vertical sliding movement on the vertically disposed guide posts 546.

Each of the plates 559 have integral therewith and projecting upwardly therefrom, bearing portions 581, the upper ends of which engage the lower surface of the plate 576, intermittently. These bearing portions 581 are also penetrated by restricted portions 582 of vertically disposed connecting rod shafts 583 (Figure 30), there being two of these shafts 583 projecting upwardly from the plates 559. These shafts 583 slidably penetrate the plate 576 and the bearing portions 585, which are integral with the plate 576, and project upwardly therefrom.

The plate 576 also has, integral therewith and extending upwardly from a medial portion thereof, a bearing portion 590 which is penetrated by a restricted portion 591 of a vertically disposed shaft 592 (Figures 22, 23 and 27). The shaft 592 is secured to the horizontally disposed plate 576, by a nut 593 which is threadably mounted on the lower end of the restricted portion 591 of the shaft 592.

The vertically disposed shaft 592 is disposed in the center of the folding and forming unit 536, and has vertical sliding movement in a bearing portion 595 which is welded to the upper surface of a fixed horizontally disposed plate 597. The plate 597 has bearing portions 600, at each end thereof, which engage shoulders adjacent the upper ends of the guide posts 546 which are formed by restricted portions 601 of the guide posts 546. The restricted portions 601 penetrate the bearing portions 600 and also penetrate the horizontally disposed portions 55 and 57 of the vertically disposed plates 35 and 54, and have threadably mounted, on the upper ends thereof, nuts 602 to thus secure the upper ends of the shafts 546 to the plates 37 and 55 and thereby support the folding and compressing and forming unit 536. The spaced vertically disposed shafts 583 have vertical sliding movement in bearing portions 604 which are also welded to the top surface of the horizontally disposed plate 597.

The dies 535 each have a groove 609, extending longitudinally thereof, which has an enlarged cylindrical surface 610, at the bottom thereof, to thus form an elong-

gated pocket for the forming and compressing of the articles A, as will be later described.

When each article A moves onto the upper surface of the die 535, in the manner heretofore described, it will be disposed in the position shown in Figure 31 and is thus in position for the folding operation. The upper end of the groove 699, in each of the dies 535, is flared at both sides, as at 611, so that, as each folding plate 568 moves downwardly and the bottom edge of the same engages the article A, that is disposed on the die 535, as shown in Figure 32, the article A will enter the groove 699 smoothly.

The folding plates 568 are caused to move, vertically, by the shaft 592 which extends upwardly and is pivotally mounted on a stub shaft 612 (Figures 22, 23 and 26) which is fixedly mounted in a forked member 613, the upper end of which is threadably penetrated by a connecting rod 615. The connecting rod 615 is secured in the upper end of the forked member 613 by a lock nut 617. The upper end of the connecting rod 615 is threadably imbedded in a forked member 618 and is secured in the same by a lock nut 619. The upper end of the forked member 618 has mounted therein one end of a lever bar 621 which is pivotally mounted on a stub shaft 622 and the stub shaft 622 is fixedly mounted in the upper end of the forked member 618.

The lever bar 621 (Figure 22) has fixedly mounted therein, intermediate its ends, a transverse shaft 624 which is oscillatably mounted in bearing blocks 625 which are secured, by any suitable means such as screws 626, to the upper surfaces of channel bars 628 and 629 (Figures 2, 3 and 62).

The free end of the lever bar 621 (Figure 22) has, projecting laterally therefrom, a stub shaft 627 having a cam follower 630 rotatably mounted thereon (Figures 5 and 22). The cam follower 630 engages a groove 631 in one side of a closed cam wheel 632 which is fixedly mounted on a transverse shaft 634. Referring to Figure 5, it may be observed that the shaft 634 is rotatably mounted in bearing blocks 635 which are secured, by any suitable means such as screws 636, to the upper surfaces of the horizontally disposed channel bars 35, 125 and 126 (Figure 4).

After the folding plates 568 have moved downwardly, from the position shown in Figure 22 to the position shown in Figures 23, 29 and 33, and have started their upward movement, the forming and compressing plates 563 then move downwardly, from the position shown in Figures 24 and 29, through the position shown in Figures 26 and 33 to the position shown in Figure 34. Figure 22 shows the folding and forming plates in their raised position and Figure 23 shows the forming plates 563 in raised position and the folding plates 568 in their lowermost position. Figure 24 shows also the folding plates 568 in their raised position, as well as the forming plates 563 and associated parts, while Figure 25 shows the folding plates 568 in raised position and the forming plates 563 are in their lowermost position.

Vertical movement is transmitted to the forming plates 563 through the two spaced vertically disposed shafts 583 which extend upwardly from the plates 559 and have relative vertical sliding movement in the bearing portions 585 of the horizontally disposed plate 576 and extend upwardly through the plate 597 and have vertical sliding movement relative to the plate 597 in the bearing portions 604.

The shafts 583 then project upwardly and the upper ends thereof are each pivotally mounted on a separate stub shaft 640 (Figures 24 and 25) which is fixedly mounted in a downwardly projecting forked member 641, the upper end of which threadably receives the lower end of a vertically disposed connecting rod 642. The connecting rod 642 is locked in the forked member 641 by a lock nut 643. The upper end of the connecting rod 642 is threadably imbedded in the lower end of a

forked member 645 and is secured in the same by a lock nut 646.

The upper ends of the forked members 645 each have, fixedly mounted therein, stub shafts 647 on which the ends of horizontally disposed arms 650 are pivotally mounted. One of the arms 650 extends rearwardly and is fixedly mounted on a shaft 651 which is rotatably mounted, at each end thereof, in bearing blocks 652 (Figures 1 and 5).

The bearing blocks 652 are secured, by any suitable means such as screws 653, to the upper surfaces of the horizontally disposed channel bars 122 and 123. The remaining arm 650, which is also pivotally mounted on one of the stub shafts 647, extends towards the rear of the machine and is also fixedly mounted on the shaft 651 (Figures 1, 5 and 24 and 25). This remaining arm 650 has, integral therewith, a rearwardly and downwardly projecting arm 655 the lower end of which has projecting from one side thereof a bearing portion 659 on which is mounted a roller 656 (Figures 24 and 25).

Disposed adjacent the arm 655 is a closed cam wheel 658 having a continuous groove 657 in one side thereof which is adapted to be engaged by the cam follower 656. The cam wheel 658 is fixedly mounted on the shaft 634 heretofore described. Thus rotation of the shaft 634 transmits vertical reciprocatory movement to the forming plates 563. The shaft 634 has the sprocket wheel 214 fixedly mounted thereon which, as has been heretofore described, has the upper end of the double sprocket chain 213 mounted thereon.

After the forming plates 563 have moved downwardly to the position shown in Figure 34, the articles are then compressed and in a position to be moved inwardly and compressed longitudinally in the bores 332 in the turret 320 as will be presently described.

There is also fixedly mounted on the shaft 453 (Figure 54), between the cam 463 and the bearing block 455, a closed cam wheel 665 having a continuous groove 666 in one side thereof. This groove 666 is adapted to be engaged by a cam follower 667 projecting from the short end of a bell crank 670. The bell crank 670 is fixedly mounted on a shaft 673, the opposed ends of which are rotatably mounted in bearing blocks 674 (Figures 5, 54 and 55). The bearing blocks 674 are secured, by any suitable means such as screws 675, to the transverse channel bars 165 and 166 which extend crosswise of the machine and are welded at their opposed ends to the horizontally disposed I-beams 21 and 22.

It may be observed in Figures 54 and 55 that the bell crank 670 has an upwardly projecting arm 680 integral therewith the upper end of which is pivotally mounted on a stub shaft 681, the opposed ends of which are fixedly mounted in a horizontally disposed forked member 682. The forked member 682 has threadably imbedded therein, one end of a horizontally disposed connecting rod 683 which is locked in the forked member 682 by a lock nut 684. The other end of the connecting rod 683 is threadably imbedded in a forked member 685 and is locked in the same by a lock nut 686. The forked member 685 is mounted between upwardly extending ears 690 (Figures 41, 54 and 55) and is pivotally mounted on a stub shaft 691 which is fixedly mounted in the upwardly extending ears 690. The upwardly extending ears 690 project upwardly from a dovetailed slide member 692 which has horizontal sliding movement on a mating dovetailed guide member 693 which extends longitudinally of the machine and is secured, by any suitable means such as welding, to the horizontally disposed bars 152 and 253 (Figure 42).

The upper dovetailed slide member 692 has, projecting therefrom, spaced compression plungers 694 each of which is in alignment with the cylindrical pocket 619 in each of the folding and forming dies 535. After the articles A have been formed and compressed in the manner heretofore described, by the forming plates 563, and before the forming plates are withdrawn from engagement with the

articles A, the horizontally disposed compressor plungers 694 are moved inwardly, by the cam wheel 665, from the position shown in Figure 36, through the position shown in Figure 37, to the position shown in Figure 38 to thus move the articles A into the turret 320 and compress them in the manner shown in Figure 38.

It may be observed in Figure 38 that, as the articles A are compressed in the bores 332 of the turret 320, the tubular containers 435 will also be moved into the uppermost row of the bores 332 simultaneously with the compression of the articles A to the position shown in Figure 38, by means to be presently described.

That bearing block 635 which is mounted on the upper surface of the channel bar 125, has, adjacent to same, fixedly mounted on the horizontally disposed shaft 634, a closed cam wheel 700 (Figures 4 and 56). This cam wheel 700 has a continuous groove 701, in one side thereof, which is engaged by a cam follower 702 rotatably mounted on a stub shaft 703 extending from the upper end of a substantially vertically disposed lever bar 704.

Intermediate the ends of the lever bar 704 there is fixedly mounted therein a stub shaft 705 which is oscillatably mounted at each end thereof in bearing blocks 706 which are secured, by any suitable means, to the vertically disposed channel bars 132 and 133 (Figures 2, 4 and 62).

The lower end of the lever bar 704 has, fixedly mounted therein, a stub shaft 708 and, the lower end of the lever bar 704, being forked, has disposed therein, and pivotally mounted on the shaft 708, a horizontally disposed member 710 which has, threadably mounted therein, one end of a connecting rod 711 which is secured to the same by a lock nut 712. The other end of the connecting rod 711 is threadably embedded in a bar 715 and is locked in the same by a lock nut 716 (Figures 53 and 56).

The bar 715 is partially disposed between ears 717 of an upper dovetailed slide 718 and fixedly mounted in the ears 717 is a stub shaft 720 on which the end of the bar 715 is pivotally mounted. Projecting to the left in Figures 53 and 56, and being fixedly mounted in the dovetailed slide 718, are back-up plungers 721, there being four of them, so that there is one disposed in alignment with each of the nests 413 as well as one for each of the bores 332 disposed adjacent one of the sides of the turret 320. The upper dovetailed slide 718 is mounted for horizontal sliding movement on a lower dovetailed guide 723 which is secured, by any suitable means such as welding, to the upper surfaces of the longitudinally extending bars 142 and 143. Thus, rotation of the cam 700 with the shaft 634 cause reciprocatory lateral movement of the back-up plungers 721 and these back-up plungers are adapted to enter the adjacent openings 421 to thus move the lowermost tubular containers 435 along the V-shaped grooves 420 of the nests 413 and thence into the adjacent bores 332 of the turret 320 as shown in Figures 37 and 38.

After the compression plungers 694 have moved inwardly to transfer the article into the bores 332 in the turret 320, being backed up by the back-up plungers 721, both of these sets of plungers will then recede to normal position simultaneously or to the position shown in Figures 54 and 53, the machine then being in position for moving the turret one fourth of a revolution for the presenting of a new row of four bores ready for a repeat of the operation.

After the tubular containers 435 and the articles A have been moved into the upper row of bores 332 in the turret 320, as shown in Figure 38, the turret 320 will then partially rotate in a clockwise direction, from the position shown in Figure 61 to the position shown in Figure 39 where the turret 320 will stop momentarily as the succeeding row of bores 332 are loaded in the same manner as the preceding row of bores, as has been heretofore described. Then the turret will rotate through the position shown in Figure 40 and finally to the position shown in Figure 58 where, with the articles A therein, the containers 435 will be discharged from the turret 320, in a

manner to be presently described. Although the turret 320 is shown in Figures 40 and 43 with the edges 327 to 339, inclusive, disposed at an angle, the turret 320 passes through this position, but does not stop in the position shown and is merely shown for purposes of clarity.

By referring to Figures 56 to 60 inclusive there may be observed the means for discharging the tubular containers 435, with the articles A disposed therein, from the lowermost row of bores 332 in the turret 320. The shaft 634 has, fixedly mounted thereon, a closed cam wheel 730 (Figures 56 and 57) having a continuous groove 731 in one side thereof. This groove 731 is engaged by a cam follower 732 rotatably mounted on a stud 733 which is fixedly mounted in a lever bar 734. The left-hand end of the lever bar 734, as observed in Figures 56 and 57, is fixedly mounted on a stub shaft 735 which projects towards the observer in Figures 56 and 57 and is rotatably mounted in a bearing block 736 (Figure 2). The lever bar 734, being very close to the bearing block 736, another bearing block is not required to support the opposite end of the shaft 735. The substantially horizontally disposed lever bar 734 has, projecting downwardly therefrom, a portion 737 which is pivotally secured, as at 739 in one end of a vertically disposed forked member 738. This forked member 738 has threadably mounted therein, the upper end of a connecting rod 741 which is secured in the same by a lock nut 742.

The lower end of the connecting rod 741 is threadably imbedded in a forked member 743 and is locked in the same by a lock nut 744. The stub shaft 745 has, fixedly mounted thereon, one end of a horizontally disposed bar 746 which extends rearwardly and has a bearing portion 747 integral therewith which is fixedly mounted on a transverse shaft 748. The transverse shaft 748 is oscillatably mounted, at each end thereof, in bearing blocks 749 which are secured, by any suitable means such as screws 750, to the horizontally disposed angle bars 137 and 138.

Fixedly mounted on the shaft 748 and projecting downwardly from the center thereof, is a substantially vertically disposed arm 755 the lower end of which is confined in a horizontally disposed forked member 756 which has, fixedly mounted therein, a transverse stub shaft 757 and the lower end of the vertically disposed bar 755 is pivotally mounted on the stub shaft 757. The forked member 756 has threadably mounted therein the right-hand end of a connecting rod 758 (Figures 56 and 57) which is secured therein by a lock nut 760. The left-hand end of the connecting rod 758, as observed in Figures 56 and 57 is threadably imbedded in a block 761 and is locked therein by a lock nut 762. The block 761 is mounted between vertically disposed ears 763 of an upper dovetailed slide member 765. The upwardly extending ears 763 have, fixedly mounted therein, a horizontally disposed stub shaft 766 on which the block 761 is pivotally mounted. The dovetailed slide member 765 is mounted for horizontal sliding movement on a dovetailed guide bar 767 which is welded to the upper surfaces of transversely disposed strap iron members 768 which are bent downwardly at each end thereof and are secured to the horizontally disposed I-beams 21 and 22, at each end thereof, by any suitable means such as bolts 770 (Figure 56).

Secured to the left-hand vertical surface of the upper dovetailed slide 765, in Figures 56 and 57, are vertically disposed bars 775, there being four of these vertically disposed bars 775 to thus cooperate with four of the bores 332 which are disposed adjacent the lowermost edge of the turret 320 (Figure 61). Near the upper ends of the vertically disposed bars 775 there are, threadably imbedded therein, and extending rearwardly therefrom, horizontally disposed ejector plungers 776. When that side of the turret 320 has moved to the lowermost position, as shown in Figures 58 to 60, the ejector plungers

776 are moved from the position shown in Figures 56 and 59 to the position shown in Figures 57 and 60, respectively, by rotation of the cam wheel 730. Thus, the tubular containers 435, with the articles A therein, are ejected from the turret and fall, by gravity, onto the top surface of the angularly disposed sloping portion 400 of the sheet metal plate 397, as observed in Figures 57 and 60, and will slide, by gravity, onto the upper reach of the conveyor belt 392 and thus be discharged into the cup portion 406 of the chute 405 and may then be picked up by the operator or directed into a suitable container.

It may be observed in Figures 2 and 46 that the sprocket chain 214 engages an idler take-up sprocket 780 which is rotatably mounted on a stub shaft 781 which projects outwardly from an angularly disposed bar 782 to which it is welded. The lower end of the bar 782 is penetrated by a bolt 783 to thus secure the same to the horizontally disposed plate 40. The angularly disposed bar 782 also has an arcuate slot 784 therethrough which is penetrated by a bolt 785 (Figure 46) which also serves to secure the angularly disposed bar 782 to the vertical surface of the horizontally disposed plate 40. Disposed above the angularly disposed bar 782, and welded to the vertically disposed angle bar 34, is an angle clip 786, which is threadably penetrated by a set screw 787, and which is secured in the angle clip 786 by a lock nut 790. The set screw 787 projects downwardly through the angle clip 786 and the lower end of the same engages the upper edge of the angularly disposed bar 782 and by loosening the bolt 785 and adjusting the set screw 787, tension may be increased or decreased on the sprocket chain 214 by the sprocket wheel 780, as desired. The bolt 785 is then tightened to thus secure the angular disposed bar 782 in position.

Method of operation

Before starting the machine it is necessary that a quantity of the tubular containers 435 be placed in the tray 430 and thus be permitted to roll, by gravity, down the chutes 425 and then down the chutes 417 to the position shown in Figure 61 where the lowermost of the tubular containers 435 rests in the V-shaped grooves 429 in the upper surfaces of the nests 413.

The belt conveyor 260 is, of course, driven by a means remote from this machine and it may be assumed that the upper reach of the conveyor belt 270 is moving from left to right in Figure 1 to thus convey articles, such as sanitary napkins A, from previous processing to this machine.

This machine may be employed for compressing and packaging not only sanitary napkins, but surgical dressings, bandages, or any similar articles, which are usually made of a web of fibres, encased in a gauze covering.

The switch 17 (Figure 1) is then closed and electric current will pass from a source of electrical energy, not shown, through the wires 18 and 19 to the wires 15 and 16 and to the magnetic switch 13, to thus cause the magnetic switch 13 to close and electric current will continue through the electric wires 11 and 12 to the electric motor 10.

The electric motor 10 will, of course, transmit rotation to the pulley 191 which will transmit rotation to the pulley 193 through the belt 192. The pulley 193, being fixedly mounted on the shaft 194, will thus transmit rotation to the gear reducing unit 200 and thus to the shaft 203 extending from the same. This will, of course, transmit rotation to the sprocket wheel 204, through the sprocket chain 205 (Figure 3) and to the sprocket wheel 207, which is fixedly mounted on the transversely disposed shaft 208.

Inasmuch as the miter gear 215 is fixedly mounted on the shaft 208, this miter gear 215 will transmit rotation to the miter gear 217 on the end of the shaft 218 (Figures 41 and 42). This shaft 218, having the sprocket wheel 227 fixedly mounted thereon, will thus transmit

rotation to the sprocket wheel 231 through the sprocket chain 230. The sprocket wheel 231, being fixedly mounted on the longitudinally disposed shaft 232, will transmit rotation to the same and, since the sprocket wheels 240 and 241 are also fixedly mounted on the shaft 232, movement will thus be imparted to the chain conveyor 243 comprising the conveyor chains 244 and 245, which are mounted on the sprocket wheels 240 and 241, respectively.

As the trays 250 of the chain conveyor 243 move from left to right in Figure 5, operators pick the articles A off of the conveyor belt 270 and place one article A in each of the trays 250, in the manner heretofore described. As the trays with the articles A therein pass by the injector clips 531 each of the articles A, disposed within the trays 250, are engaged, at one end thereof, by the downturned portions 532 of the injector clips 531. These injector clips 531 then move from the position shown in Figure 13, through the positions shown in Figures 14 and 15, to the position shown in Figure 16, and to a position where the downturned portion 532 of the injector clip 531 is adjacent the front end of the dies 535 to thus move the articles A onto the upper surfaces of the dies 535 or, in other words, to the position shown in Figure 31.

This movement of the injector clips 531 is transmitted to the same through the vertically disposed arm 487 which is fixedly mounted at its upper end on the shaft 485, said shaft 485 having the other arm 483 integral therewith which extends towards the front of the machine and is pivoted at the upper end of the connecting rod 476, the lower end of which is pivotally mounted as at 474 to the bell crank 467. Reciprocatory movement is imparted to the bell crank 467 by the cam follower 465 which projects from the same and engages the cam wheel 463. The other end of the bell crank 467 is fixedly mounted on the shaft 471 which is pivotally mounted in the bearing blocks 472. The cam wheel 463 being fixedly mounted on the transverse shaft 453, is rotated by the same, rotation being transmitted to the shaft 453 by the sprocket wheel 452 on which the sprocket chain 451 is mounted. The sprocket chain 451 is also mounted on the sprocket wheel 450, which is fixedly mounted on the transverse shaft 268 which is driven in the manner heretofore described.

It is evident from the configuration of the closed groove 464 in the cam wheel 463 (Figures 2, 3, 13 and 14) and the relative lengths of the connecting rod 476, the arm 483 and the arm 487, that the cam wheel 463 will cause very rapid reciprocation of the injector clips 531 so the trays 250, which move at a relatively slow rate with the conveyor chains 244 and 245, may continue movement during reciprocation of the injector clips 531. As heretofore stated, it will be noted in Figure 20 that the forward wall 258 of each tray 250 is bent forwardly at 259 so that, while the conveyor 243 is continuously moving, the quick reciprocatory movement imparted to the bar 496 will cause the downturned ends 532 of the injector clips 531 (Figure 16) to slide past the rear surface of the forwardly bent portion 259 and thus will move past the uprising member 257 of each of the clips 256 even though they are moving with the conveyor 243.

After the clips 531 have completed their inward stroke, they will be returned in an elevated position due to the fact that the rollers 500 on the ends of the horizontally disposed plate 496 will elevate the downturned ends 532 of the clips 531 above the level of the walls 258 of the trays 250 on their return stroke by the means shown especially in Figures 17 and 18. In view of the fact that the speed of the stroke of the injector clips 531 is very swift in comparison with the speed of the endless conveyor 243 on which trays 250 are mounted, there will be no smashing of parts although the conveyor is moving at the time the clips 531 travel into the trays 250.

The articles A are then automatically folded, in the manner shown in Figure 32, by the vertically disposed folding plates 568. These plates 568 are secured to the lower surface of the horizontally disposed plate 576, as heretofore described, and this plate 576 is mounted for vertical sliding movement at each end thereof on the vertically disposed guide posts 546. Reciprocatory movement is transmitted to the plate 576 by the shaft 592, the lower end of which is secured to the plates 576 by the nut 593 and which is mounted on the restricted portion 591 of the shaft 592 (Figure 30).

This shaft 592 projects upwardly, as viewed in Figures 22 and 23, and is connected to the lower end of the vertically disposed connecting rod 615 in the manner heretofore described. The upper end of the connecting rod 615, of course, is connected to one end of the substantially horizontally disposed lever bar 621, it being pivoted at 624 and having the cam follower 630 on the other end thereof. This cam follower 630 engages the groove 631 in the cam wheel 632, said cam wheel 632 being fixedly mounted on the transversely disposed shaft 634. This shaft 634 is driven by the sprocket wheel 214 which is also fixedly mounted on the shaft 634, said shaft being rotatably mounted in bearing blocks 635 which are in turn fixedly mounted on the horizontally disposed channel bars 35, 125 and 126 (Figures 2, 4 and 5).

The sprocket wheel 214 is driven by the sprocket chain 213 which projects downwardly and forwardly in Figure 2 and is mounted at its lower end on the sprocket wheel 212 which is fixedly mounted on the outer end of the shaft 208. Thus, vertical reciprocatory movement is transmitted to the vertically disposed folding plates 568.

The forming and compressing plates 563 are then moved downwardly, part of this downward movement taking place simultaneously with the withdrawing, or upward movement, of the vertically disposed folding plates 568, as observed in Figure 33. The lowermost edges of the plates 563 then engage the opposed upturned edges of the articles A and move and compress the same downwardly into the cylindrically shaped pocket 610 of the dies 535, from the position shown in Figure 33 to the position shown in Figure 34. It may be noted that, due to the angularly cut surfaces 564, at the lower edges of the vertically disposed forming plates 563, the sanitary napkins A or similar articles will thus be formed into an elongated mass which is substantially round in cross-section (Figures 35 to 37 inclusive).

Vertical reciprocatory movement is transmitted to the vertically disposed forming plates 563, due to the fact that their upper edges engage the lower surfaces of the horizontally disposed plates 556, 559 and 561 to which they are secured in the manner heretofore described. The horizontally disposed plates 556 are welded to the same cross members 557 and 558 that the plates 559 and 561 are welded to and these plates 556 have vertical sliding movement, at each end thereof, on the vertically disposed guide posts 546 and, secured to the plates 559, and projecting upwardly therefrom, are the vertical disposed shafts 583 (Figures 24, 25, 29 and 30). The shafts 583 project upwardly and are pivotally connected to the lower ends of the vertically disposed connecting rods 642 in the manner heretofore described, and the upper ends of the connecting rods 642 are pivotally connected to one end of each of the horizontally disposed arms 650.

It has already been described how both of the horizontally disposed bars 650 extend rearwardly and are fixedly mounted on the horizontally disposed transverse shaft 651, and that only one of the bars 650 has the arm 655 projecting rearwardly and downwardly therefrom. Oscillatable movement is transmitted to the left-hand ends of the arms 650, as observed in Figure 24, by the rearwardly and downwardly projecting arm 655 which has the cam follower 656, on the end thereof, engaging the groove 657 of the cam wheel 658. This cam wheel 658 is fixedly

mounted on the transverse shaft 634 which is driven in the manner heretofore described.

After the articles A have been formed into the substantially cylindrically shaped mass, as shown in Figure 35, the compressor plungers 694 move into the enlarged cylindrical pockets 610, at the bottom of the dies 535, from the position shown in Figure 36 to the position shown in Figure 37, and finally to the position shown in Figure 38, and the compressor plungers 694 are then withdrawn from the dies 535 to return to the position shown in Figure 36 and to remain in this position until the turret 320 has rotated 90°, to a different position, in a manner to be later described.

This horizontal reciprocatory step-by-step motion, of the horizontally disposed compressor plungers 694, is transmitted to the same in the manner shown in Figures 54 and 55. It has already been described how the horizontally disposed compressor plungers are secured in the upper dovetailed slide 692, which has horizontal sliding movement on the lower dovetailed guide 693. This dovetailed slide 692 is, of course, pivotally connected to the horizontally disposed connecting rod 683, by means hereinto described, and the other end of this connecting rod 683 is pivotally connected to the upper end of the arms 680, of the bell crank 670. The junction point of the two arms of the bell crank 670 is fixedly mounted on the shaft 673 which is rotatably mounted in the bearing blocks 674 (Figures 5, 54 and 55). Oscillatable movement is transmitted to the bell crank 670 by the cam follower 667 which projects from the same and engages the groove 666 in the side of the cam wheel 665. The cam wheel 665 is fixedly mounted on the shaft 453 which is driven by the sprocket wheel 452, in the manner heretofore described.

Simultaneously with the inward movement of the horizontally disposed compressor plungers 694, the back-up plungers 721 also move inwardly through the openings 421 (Figure 52) in the lower ends of the vertically disposed chutes 417 to thus engage one end and move the lowermost of the tubular containers 435 along the V-shaped grooves 429, in the upper surfaces of the nests 413, to move the tubular containers 435 into the turret 320 to the position shown in Figure 38. The back-up plungers 721 then move, in the opposite direction, out of the path of the next succeeding tubular container 435 disposed thereabove and thus the next succeeding tubular container 435 will fall, by gravity, into position for the next cycle in the operation of this machine.

This reciprocatory step-by-step horizontal movement of the back-up plungers 721, is due to the fact, that the back-up plungers 721 are fixedly mounted in the dovetailed slide 718 (Figures 53 and 56). The dovetailed slide 718 has horizontal sliding movement on the dovetailed guide bar 723 which is welded to the longitudinally extending bars 142 and 143 (Figure 61). The dovetailed slide 718 has pivotally connected thereto, at 720, the horizontally disposed connecting rod 711, in the manner heretofore described. The other end of the connecting rod 711 is pivotally connected to the lower end of the substantially vertically disposed lever bar 704 which is pivotally mounted at its center on the stub shaft 705 and at its upper end it has projecting therefrom the cam follower 702 which engages the groove 701 in the cam wheel 700.

The cam wheel 700 is fixedly mounted on the shaft 634 which is rotated in the manner heretofore described. Thus, it is seen that as the cam wheel 700 rotates with the shaft 634, the lower end of the lever bar 704 reciprocates to thus transmit reciprocatory step-by-step movement to the horizontally disposed back-up plungers 721.

After the tubular containers 435 and the articles A have been moved into the uppermost row of the bores 332, in the turret 320, the turret moves from the position shown in Figure 61, in a clockwise direction, to the position shown in Figure 39, in which position it will stop

momentarily as the succeeding bores 332, which are disposed adjacent the edge 328, of the turret 320, receive the tubular containers 435 and the articles A in a manner identical to that in which the bores 332, which are disposed adjacent the edge 327, received them.

When the bores 332, having the containers 435 and the articles A therein, are in the position shown in Figure 39, they are not acted upon in any manner. However, it is necessary that the turret 320 stop momentarily at every 90° so that while the turret 320 is in the position shown in Figure 39 the bores 332 adjacent the opposite vertical edge of the turret 320, which, in this instance, is the edge 329, will momentarily stop in alignment with the means of directing blasts of air through the bores 332 to remove any foreign matter from the bores 332 in a manner to be later described.

This step-by-step rotation of the turret 320 is transmitted to the same from the shaft 310 on which the turret 320 is fixedly mounted. The shaft 310 is rotatably mounted in the bearing blocks 311 and 312, as heretofore described, and there is fixedly mounted thereon, the pinion 307. The pinion 307 meshes with the gear 306 which is fixedly mounted on the shaft 300 (Figure 43).

The shaft 300 also has mounted thereon a star wheel 298 (Figures 41, 42 and 43) which has the slots 297 therein and these slots 297 are adapted to be engaged, one at a time, by the roller 295 (Figure 45) which is rotatably mounted on the stud 294 extending from the outwardly projecting portion 293 of the Geneva motion driving member 290.

By referring to Figures 41 to 44, inclusive, it may be observed that the Geneva motion driving member 290 is fixedly mounted on the shaft 281. Rotation of this shaft 281 causes the roller 295 to revolve around the shaft 281. During the time that the turret 320 is momentarily stopped, in a position such as that shown in Figures 41 and 61, that portion 291 of the Geneva motion driving member 290 which is opposite from the roller 295, engages one of the arcuate surfaces 299 which are disposed between the radial slots 297 of the star wheel 298. This will, of course, lock the star wheel 298, in a position such as that shown in Figure 42 and thus cause the turret 320 to remain in the position shown in Figure 42 until the roller 295 has engaged that slot 297 which is disposed, in this instance, immediately below the arcuate portion 299 with which the convex surface 291 of the Geneva motion driving member 290 is in engagement. As the roller 295 engages this groove 297, the convex surface 291, of the Geneva motion driving member 290, is moved out of engagement with the arcuate surface 299 and the portion of the star wheel 298, in which the groove 297 is disposed, passes through the area that is defined by the concave portion 292 of the Geneva motion driving member 290. This will cause the star wheel 298 to partially rotate, in a clockwise direction, from the position shown in Figure 42, through the position shown in Figure 43 and to rotate the star wheel 60° or to a position identical to that shown in Figure 42 but advanced one step. This operation is, of course, repeated with every revolution of the shaft 281.

When the star wheel 298 rotates the 60° as heretofore described, the gear 306 will, of course, rotate 60° and will thus cause the pinion 307, with which it is engaged, to rotate 90°, which will thus impart rotation to the turret 320 to cause the turret to move 90° since the pinion 307 and the turret 320 are fixedly mounted on the same shaft 310.

The shaft 281, on which the Geneva motion driving member 290 is fixedly mounted, also has fixedly mounted thereon a miter gear 280 (Figures 41 and 42). This miter gear 280 is in engagement with the miter gear 216 which is fixedly mounted on the shaft 208, said shaft being driven in the manner heretofore described. It is

thus seen how the turret 320 is caused to rotate in step-by-step relation, 90° at a time.

When the turret 320 has rotated in step-by-step relation to where the bores 332, having the tubular containers 435 and the articles A therein, are in the position shown in Figure 58, the tubular containers 435 are each engaged by one end of the ejector plungers 776, which are then moved into the bores 332, which are disposed in alignment therewith, to thus move the articles A and the tubular containers 435, associated therewith, out of the lowermost bores 332, or, from the position shown in Figure 59 to the position shown in Figure 60. The ejector plungers 776 are then caused to withdraw from the bores 332 to the position shown in Figure 59.

This reciprocal movement of the ejector plungers 776 is due to the fact that the ejector plungers 776 are threadably imbedded in the upper ends of the vertically disposed bars 775, which are secured at their lower ends to the dovetailed slide 765. This dovetailed slide 765 is slidably mounted on the dovetailed guide 767 and is caused to reciprocate laterally by being pivotally connected to one end of the horizontally disposed connecting rod 758 (Figure 57), in the manner heretofore described, and the other end of the connecting rod 758 being connected to the lower end of the substantially vertically disposed bar 755, in the manner heretofore described.

The upper end of the bar 755 is fixedly mounted on the shaft 748 and oscillatable movement is imparted through the shaft 748 to the bar 755 inasmuch as the horizontally disposed bar 746 is also fixedly mounted on the shaft 748. This shaft 746 has, pivotally secured to the other end thereof, the vertically disposed connecting rod 741 which is connected, at its upper end, to the downwardly projecting portion 737 of the horizontally disposed bar 734, both ends of the connecting rod 741 being pivotally connected in the manner heretofore described. The horizontally disposed bar 734 is fixedly mounted on the shaft 735 which is oscillatably mounted in the bearing block 736 (Figure 2) as heretofore described. The other end of the lever bar 734 has the stud 733 therein on which the cam follower 732 is rotatably mounted and which in turn engages the groove 731 in the vertical face of the cam wheel 730 which is fixedly mounted on the shaft 634 driven by means heretofore described. It is thus seen that the ejector plungers 776 are caused to move into the bores 332 disposed near the lower edge of the turret 320 by the cam wheel 730 on the shaft 634.

After the tubular containers 435, with the articles A disposed therein, have been moved out of the lowermost bores 332 in the turret 320, they are caused to slide, by gravity, down the angularly disposed portion 409 (Figures 57 and 60) and are deposited on the conveyor belt 392, by gravity. The conveyor belt 392, being mounted on the pulleys 391 and 393, will then carry the tubular containers 435, and the articles A disposed therein, to the left-hand end of the conveyor belt, as observed in Figures 58 and 61, to thus cause the same to roll down the inclined surface of the chute 504 into the cup portion 406 where they are picked up by an operator.

The pulley 391, on which one end of the conveyor belt 392 is mounted, is fixedly mounted on the shaft 384 which is rotatably mounted in the bearing blocks 386. On the other hand, the other end of the conveyor belt 392 is mounted on the pulley 393 which is fixedly mounted on the shaft 394 which is, in turn, rotatably mounted in the bearing blocks 395. The shaft 384 is driven by the sprocket wheel 383 which is fixedly mounted thereon and is engaged by the sprocket chain 336 (Figure 46), one end of which is mounted on the sprocket wheel 335 which is fixedly mounted on the shaft 281. The shaft 281 is the same shaft on which the Geneva motion driving member 290 is fixedly

mounted and it has therefore been described how this shaft 281 is driven.

The other end of the sprocket chain 336, as observed in Figure 46, is mounted on the sprocket wheel 337 which is fixedly mounted on the shaft 338. This shaft 338 has mounted thereon the cam wheel 345 (Figure 48) which has the outwardly extending lobe 346 integral therewith. After the bores 332, disposed adjacent the lower edge of the turret 320, have had the tubular containers 435, with the articles A therein, ejected from the same, in the manner heretofore described, the turret 320 is caused to rotate another 90° in the manner heretofore described.

It may be observed in Figures 47 and 39 that the bores 332 are then disposed in alignment with the nipples 373 and the uppermost nipple 377 (Figure 47). Blasts of air are emitted from the nipples 373 and 377, intermittently, and this is caused by the lobe 346 on the cam wheel 345 engaging one end of the plunger 350 which has horizontal sliding movement in the valve housing 351 (Figures 48 and 49). This valve housing 351 has the nipple 362 leading thereto from a pipe 364 which is connected to the compressed air tank 368, and this nipple 362 permits ingress of compressed air into the chamber 357. When the plunger 350 is moved, so that the collar 356, of the same is moved out of the opening 355 in the partition 354 of the valve housing 351, the compressed air will then pass through the chamber 357, into the chamber 358 and thus into the union 365 and into the flexible hose 366. The other end of the flexible hose, being connected to the lower end of the vertically disposed pipe 371, then directs the compressed air to the pipe 371 and the air is then directed through the nipples 373 and 377, which are connected to the vertically disposed pipe 371, to emit a blast of air from each of the same. The blasts of air from the nipples 373 and 377 remove any loose material, such as lint, from the bores 332 disposed in alignment with the same. This completes a cycle in the operation of this machine and inasmuch as all the cam wheels are in timed relation to each other, it is obvious that various of the operations will take place simultaneously on different groups of four of the articles A and the tubular containers 435.

It is preferable to fabricate the napkins A with the fibres extending longitudinally thereof so that when the articles are folded longitudinally and then compressed into an elongated cylindrical mass in the forming dies, and are then compressed longitudinally in the containers, they will be compressed short of the fatigue point of the fibres, so that when they are removed from the containers, the natural resiliency in the fibres will cause the articles to spring back, especially when the ends of the article are pulled apart, to their original length, and thus lumpiness in the fibres forming the filling will be avoided.

The sanitary napkin or other similar article A is usually formed from a web or mass of fibres 800 which during picking and other preparatory operations have their fibres parallelized and extending longitudinally of the napkin, as indicated at 801, and a suitable gauze covering 802 is wrapped around the napkin longitudinally thereof, the napkin being conventional except that it is preferable to have the bulk of the fibres 800 extending longitudinally of the napkin for the reasons above stated.

In the drawings and specification, there has been set forth a preferred embodiment of the invention, and although specific terms are employed, they are used in a generic and descriptive sense only and not for purposes of limitation, the scope of the invention being defined in the claims.

I claim:

1. A machine for folding, compressing and packaging fibrous articles, such as sanitary napkins, surgical dressings, and the like, in a suitable confining carton, com-

prising means for conveying a plurality of the articles spaced from each other, a plurality of fixed forming dies each having an open side and open ends disposed alongside the conveying means, means for transferring simultaneously a given number of the articles from the conveying means to a like number of the forming dies, each article being transferred to a separate forming die, means for entering one side of each of the forming dies and folding the articles midway of the same and longitudinally thereof, means for entering the open sides of the dies and compressing the articles laterally into an elongated mass, a movable member having a plurality of sets of open-ended bores therein, means for feeding a plurality of cartons open at each end into the bores in a given set, there being a single carton fed into each of the bores, means for compressing the articles longitudinally while under lateral compression in the forming dies and ejecting one of the same into each of the cartons while disposed in said bores, the means for feeding the cartons into the bores remaining in position while the articles are moved into the cartons by the means for compressing the articles longitudinally, means for moving the movable member to cause the set of bores coinciding with the forming dies to move to another position and to present another set of bores in alignment with the forming dies, means for ejecting the cartons with the compressed articles therein from the movable member, while another set of cartons is moved into another set of bores, and means for removing waste matter from the bores from which the cartons have been ejected.

2. In a structure according to claim 1, the means for removing waste material matter from the bores comprising a plurality of nozzles aligned with the bores and means for forcing a blast of air through each of the nozzles to project the blasts of air through the bores to remove waste matter therefrom.

3. In a structure according to claim 1, each end of the carton being open and being of smaller inside diameter than the remainder of the carton to thereby capture and confine the longitudinal compression in the article disposed within the carton.

4. In a structure according to claim 1, the forming dies each having a substantially U-shaped trough extending longitudinally thereof which is open at its upper end the folding means comprising a blade movable downwardly centrally of the trough to fold the articles longitudinally in face to face relation and the compressing means being adapted to move downwardly on each side of the blade and means for retracting the folding means while the forming and compressing means are moving downwardly into the U-shaped troughs.

5. A machine for folding, compressing and packaging fibrous articles, such as sanitary napkins, surgical dressings, and the like, in a suitable confining carton, comprising means for conveying a plurality of the articles spaced from each other, a plurality of fixed forming dies disposed alongside the conveying means, means for transferring simultaneously a given number of the articles from the conveying means to a like member of the forming dies, each article being transferred to a separate forming die, means for entering the forming dies and folding each of the articles midway of the same and longitudinally thereof, means for entering each of the dies and compressing each of the articles laterally into an elongated

mass, a movable member having a plurality of sets of open ended bores therein, means for feeding a plurality of cartons open at each end into the bores in a given set, there being a single carton fed into each of the bores, means for compressing the articles longitudinally while under lateral compression in the forming dies and ejecting one of the same into each of the cartons while disposed in said bores, the means for feeding the cartons into the bores remaining in position while the articles are moved

70 into the cartons under longitudinal compression, means

for moving the movable member to cause the set of bores coinciding with the forming dies to move to another position and to present another set of bores in alignment with the forming dies, means for ejecting the cartons with the compressed articles therein from the movable member, while another set of cartons is moved into another set of bores, and means for removing waste matter from the bores from which the cartons have been ejected.

6. In a structure according to claim 5, the forming dies each having a substantially U-shaped trough extending longitudinally thereof which is open at its upper end, the folding means comprising a blade movable downwardly centrally of each of the troughs to fold the articles longitudinally in face to face relation and the compressing means being adapted to move downwardly on each side of the blade and means for retracting the folding means while the forming and compressing means are moving downwardly into the U-shaped troughs.

7. A machine for folding, compressing and packaging fibrous articles, such as sanitary napkins, surgical dressings, and the like, in a suitable confining carton having one end open, comprising means for conveying a plurality of the articles spaced from each other, a plurality of fixed forming dies disposed alongside the conveying means, means for transferring simultaneously a given number of the articles from the conveying means to a like number of the forming dies, each article being transferred to a separate forming die, means for entering each of the forming dies and folding each of the articles midway of the same and longitudinally thereof, means for entering the dies and compressing each of the articles laterally into an elongated mass, a movable member having a plurality of sets of open-ended bores therein, means for feeding a plurality of cartons, open end first into the bores in a given set, there being a single carton fed into each of the bores, means for compressing the articles longitudinally while under lateral compression in the forming dies and ejecting one of the same into each of the cartons while disposed in said bores, the means for feeding the cartons into the bores remaining in position while the article is moved into the carton under longitudinal compression, means for moving the movable member to cause the set of bores coinciding with the forming dies to move to another position and to present another set of bores in alignment with the forming dies, means for ejecting the cartons with the compressed articles therein from the first-named set of bores in the movable member, while another set of cartons is moved into another set of bores, and means for removing waste matter from the bores from which the cartons have been ejected.

8. In a structure according to claim 7, the forming dies each having a substantially U-shaped trough extending longitudinally thereof which is open at its upper end, the folding means comprising a blade movable downwardly centrally of each of the troughs to fold the articles longitudinally in face to face relation and the compressing means being adapted to move downwardly on each side of the blade and means for retracting the folding means while the forming and compressing means are moving downwardly into the U-shaped troughs.

9. A machine for folding, compressing and packaging fibrous articles, such as sanitary napkins, surgical dressings, and the like, in a suitable open-ended confining carton whose open end is restricted, comprising means for conveying a plurality of the articles spaced from each other, a plurality of fixed forming dies disposed alongside the conveying means, means for transferring simultaneously a given number of the articles from the conveying means to a like number of the forming dies, each article being transferred to a separate forming die, means for entering each of the forming dies and folding each of the articles midway of the same and longitudinally thereof, means for entering each of the dies and compressing the articles laterally into an elongated mass, a movable mem-

ber having a plurality of sets of bores therein whose ends are open, means for feeding a plurality of cartons open end first into one of the sets of bores, there being a single carton fed into each of the bores, means for compressing the articles longitudinally while under lateral compression in the forming dies and ejecting one of the same into each of the cartons while disposed in said bores, the means for feeding the cartons into the bores remaining in position while the articles are moved into the cartons under longitudinal compression, means for moving the movable member to cause the set of bores coinciding with the forming dies to move to another position and to present another set of bores in alignment with the forming dies, means for ejecting the cartons with the compressed articles therein from the movable member, while another set of cartons is moved into another set of bores, and means for removing waste matter from the bores from which a plurality of cartons have been ejected.

10. In a structure according to claim 9, the forming dies each having a substantially U-shaped trough extending longitudinally thereof which is open at its upper end, the folding means comprising a blade movable downwardly centrally of the trough to fold each of the articles longitudinally in face to face relation and the compressing means being adapted to move downwardly on each side of the blade and means for retracting the folding means while the forming and compressing means are moving downwardly into the U-shaped troughs.

11. Apparatus for folding and compressing a fibrous article such as a sanitary napkin and depositing the same under compression in a suitable container comprising at least one forming die having a substantially U-shaped trough therein, means for folding the article into said trough longitudinally of itself, means for compressing the article laterally in said trough to reduce its thickness, means for holding an open-ended container adjacent one end of said trough, means for compressing the article longitudinally while held under lateral compression and ejecting the same from the trough into the container and compressing the article to an overall length of less than that of the container, said container having a restricted open end through which the article is forced into the container to thus retain the article within the container, means for moving the holding means for the container to another position and presenting a new holding means adjacent said end of the trough, means for ejecting the container having the compressed article therein from the holding means, while another article is being forced into another container in the holding means, and means for removing waste from the holding means from which a container has been ejected.

12. In a structure according to claim 11, the container being tubular and open at both ends and having each end thereof restricted to capture and hold the compression in the article which is placed into the container in compressed condition.

13. In a structure according to claim 11, the holding means having a plurality of bores therein for holding said containers, the means for removing waste material from the holding means comprising a plurality of nozzles aligned with the bores and means for forcing a blast of air through each of the nozzles to project the blasts of air through the bores to remove waste matter therefrom.

14. Apparatus for folding and compressing a fibrous article such as a sanitary napkin and depositing the same under compression in a suitable open-ended carton comprising at least one forming die having a substantially U-shaped trough therein, means for folding the article into said trough longitudinally of itself, means for compressing the article laterally in said trough to reduce its overall diameter, means for holding an open-ended carton adjacent one end of said trough, means for compressing the article longitudinally while held under lateral compression and ejecting the same from the trough into the carton and compressing the article to an overall

length of less than that of the carton, said carton being restricted at the end through which the article is forced into the carton to thus retain the article under compression within the carton, means for moving the holding means for the carton to another position and presenting a new holding means adjacent said end of the trough, means for ejecting the carton having the compressed article therein from the holding means, while another article is being forced into another carton in the holding means, and means for removing waste from the holding means from which a carton has been ejected.

15. In a structure according to claim 14, the carton being tubular and open at both ends and having each end thereof restricted to capture and hold the compression in the article which is placed into the carton in compressed condition.

16. Apparatus for folding and compressing a fibrous article, having the fibres extending longitudinally thereof, such as a sanitary napkin and depositing the same under longitudinal compression in a suitable open-ended carton comprising at least one forming die having a substantially U-shaped trough therein, means for folding the article into the trough longitudinally of itself, means for compressing the article laterally in said trough to reduce its overall diameter, means for holding an open-ended carton adjacent one end of the trough, means for compressing the article longitudinally while held under lateral compression and ejecting the same from the trough into the carton and compressing the article to an overall length of less than that of the carton, said carton being restricted at its end through which the article is forced into the carton to thus retain the article within the carton, means for moving the holding means for the carton to another position and presenting a new holding means adjacent the end of the trough, means for ejecting the carton having the compressed article therein from the holding means, while another article is being forced into another carton in the holding means, and means for removing waste from the holding means from which a carton has been ejected.

17. In a structure according to claim 16, the carton being tubular and open at both ends and having each end thereof restricted to capture and hold the compression in the article which is placed into the carton in compressed condition.

18. Apparatus for folding and compressing a fibrous article such as a sanitary napkin and depositing the same under compression in a suitable open-ended carton comprising a die having a substantially U-shaped trough therein, means for folding the article into said trough longitudinally of itself, means for compressing the article laterally in said trough to reduce its thickness, means for holding an open-ended carton adjacent one end of said trough, means for compressing the article longitudinally while held under lateral compression and ejecting the same from the trough into the carton and compressing the article to an overall length of less than that of the carton, means for moving the holding means for the carton to another position and presenting a new holding means adjacent said end of the trough, means for ejecting the carton having the compressed article therein from the holding means, while another article is being forced into another carton in the holding means, and means for removing waste from the holding means from which a carton has been ejected.

19. In a structure according to claim 18, the carton being tubular and open at both ends and having each end thereof restricted to capture and hold the compression in the article which is placed into the carton in compressed condition.

20. Apparatus for compressing and placing in suitable cartons fibrous articles such as sanitary napkins, surgical dressings, bandages, and the like, comprising a conveyor having a plurality of spaced trays thereon and onto which the articles are adapted to be placed, a plurality of forming dies disposed alongside the conveyor having the

trays thereon, means for transferring a given number of the articles from the trays to a like number of the forming dies, each article being transferred to a separate forming die, means entering each of the forming dies for folding each of the articles upon itself, compressing means movable into the forming dies to compress and form the articles into an elongated mass, a turret having a plurality of sets of bores disposed along its periphery, means for imparting step-by-step movement to the turret, means for feeding tubular cartons into a set of bores, there being a single carton fed into each of the bores, means for ejecting one of the compressed articles from the forming dies into each of the cartons disposed in said bores, means for ejecting the cartons from the bores after the turret has moved away from the position where it received the articles into the cartons, means for cleaning the bores of any waste matter after the cartons have been ejected therefrom, and means for conveying the ejected cartons away from the machine after they have been ejected from the turret.

21. In a structure according to claim 20, the means for cleaning the bores of any waste matter comprising a plurality of nozzles aligned with the bores and means for forcing a blast of air through each of the nozzles to project the blasts of air through the bores to remove waste matter therefrom.

22. In a structure according to claim 20, each end of the carton being open and being of smaller inside diameter than the remainder of the carton to thereby capture and confine the longitudinal compression in the article disposed within the container.

23. In a structure according to claim 20, the means for imparting step-by-step partial rotation to the turret comprising a Geneva stop mechanism for driving the turret to impart a partial rotation thereto for each revolution of the Geneva stop mechanism.

24. In a structure according to claim 20, the means for feeding the cartons into the turret comprising a plurality of vertically disposed magazines having aligned openings in opposed sides thereof, means for feeding the cartons into the magazine, plungers for passing through the aligned openings and removing the lowermost carton and forcing it into a bore, means for moving the plungers through the aligned openings in the magazines and forcing the cartons into the bores and remaining in position to close that end of the cartons while the ejecting means moves the articles from the corresponding forming dies into the cartons disposed in the bores in the turret.

25. In a structure according to claim 20, the turret being square in elevation and having a plurality of bores disposed in a straight line on each of the four sides thereof which are adapted to align with the plurality of forming dies and whereby one of a plurality of cartons can be placed into each of the plurality of bores on one side of the turret and one of a plurality of articles can be moved into each of the cartons in the turret and compressed in the cartons.

26. In a structure according to claim 20, the turret being square in elevation and having a plurality of bores along each of the four edges thereof and the means for imparting rotation to the turret in step-by-step relation moving the turret a quarter revolution at a time to align the bores in one of the four side edges of the turret with the plurality of forming dies for the reception of the compressed articles from the forming dies.

27. In a structure according to claim 20, wherein the conveyor having the trays thereon is moved continuously and the means for moving the articles off the trays into the forming dies are moved intermittently, and in which the means for longitudinally compressing the articles in the forming dies and ejecting them into the cartons disposed within the turret are moved intermittently.

28. In a structure according to claim 20, the means for transferring the articles from the trays to the forming dies being adapted to move along the bottom of said trays and guiding means for raising the transferring means

from off the bottom of the trays so that the transferring means will return at a higher elevation than that occupied while transferring the articles from the trays to the forming dies.

29. Apparatus for compressing and placing in suitable cartons fibrous articles such as sanitary napkins, surgical dressings, bandages, and the like, comprising a conveyor having a plurality of spaced trays thereon and onto which the articles are adapted to be placed, a plurality of forming dies disposed alongside the conveyor having the trays thereon, means for transferring a given number of the articles from the trays to a like number of the forming dies, each article being transferred to a separate forming die, means entering each of the forming dies for folding each of the articles upon itself, compressing means movable into the forming dies to compress and form the articles into an elongated mass, a rotary turret having a plurality of sets of transverse bores disposed along its periphery, means for imparting step-by-step movement to the turret, means for feeding tubular cartons into the bores, there being a single carton fed into each of the bores, means for ejecting one of the compressed articles from the forming dies into each of the cartons disposed in said bores and compressing the articles to a length which is less than the length of the cartons, means for ejecting the cartons from the bores after a set of bores in the turret has moved away from the position where it received the articles into the cartons, means for cleaning the bores of any waste matter after the cartons have been ejected therefrom, and means for conveying the ejected cartons away from the machine after they have been ejected from the turret.

30. In a structure according to claim 29, the means for imparting step-by-step rotation to the turret comprising a Geneva stop mechanism for driving the turret to impart a partial revolution thereto for each revolution of the Geneva stop mechanism.

31. In a structure according to claim 29, each end of the carton being open and being of smaller inside diameter than the remainder of the carton to thereby capture and confine the longitudinal compression in the article disposed within the container.

32. In a structure according to claim 29, the means for feeding the cartons into the turret comprising a plurality of vertically disposed magazines having aligned openings in opposed sides thereof, means for feeding the cartons into the magazine, plungers for passing through the aligned openings and removing the lowermost carton and forcing it into a bore, means for moving the plungers through the aligned openings in the magazines and forcing the cartons into the bores and remaining in position to close that end of the cartons while the ejecting means moves the articles from the corresponding forming dies into the cartons disposed in the bores in the turret.

33. In a structure according to claim 29, the turret being square in elevation and having a plurality of bores disposed in a straight line on each of the four sides thereof which are adapted to align with the plurality of forming dies and whereby one of a plurality of cartons can be placed into each of the plurality of bores on one side of the turret and one of a plurality of articles can be moved into each of the cartons in the turret and compressed in the cartons.

34. In a structure according to claim 29, the turret being square in elevation and having a plurality of bores along each of the four edges thereof and the means for imparting rotation to the turret in step-by-step relation moving the turret a quarter revolution at a time to align the bores in one of the four side edges of the turret with the plurality of forming dies for the reception of the compressed articles from the forming dies.

35. In a structure according to claim 29, wherein the conveyor having the trays thereon is moved continuously and the means for moving the articles off the trays into the forming dies are moved intermittently, and in

which the means for longitudinally compressing the articles in the forming dies and ejecting them into the containers disposed within the turret are moved intermittently.

36. In a structure according to claim 29, the means for transferring the articles from the trays to the forming dies being adapted to move along the bottom of said trays and guiding means for raising the transferring means from off the bottom of the trays so that the transferring means will return at a higher elevation than that occupied while transferring the articles from the trays to the forming dies.

37. Apparatus for compressing and placing in suitable cartons fibrous articles such as sanitary napkins, surgical dressings, bandages, and the like, comprising a conveyor having a plurality of spaced trays thereon and onto which the articles are adapted to be placed, a plurality of forming dies disposed alongside the conveyor having the trays thereon, means for transferring a given number of the articles from the trays to a like number of the forming dies, each article being transferred to a separate forming die, means entering each of the forming dies for folding each of the articles upon itself, compressing means movable sidewise into the forming dies to compress and form the articles into an elongated mass, a movable turret having a plurality of sets of transverse bores disposed therethrough, means for imparting step-by-step movement to the turret, means for feeding tubular open-ended cartons into a given set of the bores, there being a single carton fed into each of the bores, means for ejecting each of the compressed articles from the forming dies into a corresponding one of the cartons disposed in said bores through an open end thereof, means for ejecting the cartons from the bores after the turret has moved away from the position where it received the articles into the cartons, and means for cleaning the bores of any waste matter after the cartons have been ejected therefrom.

38. In a structure according to claim 37, wherein the conveyor having the trays disposed thereon is moved continuously and the means for moving the articles off the trays into the forming dies are moved intermittently, and in which the means for longitudinally compressing the articles in the forming dies and ejecting them into the cartons disposed within the turret are moved intermittently.

39. In a structure according to claim 37, the means for transferring the articles from the trays to the forming dies being adapted to move along the bottom of said trays and guiding means for raising the transferring means from off the bottom of the trays so that the transferring means will return at a higher elevation than that occupied while transferring the articles from the trays to the forming dies.

40. Apparatus for compressing and placing in tubular open-ended cartons fibrous articles such as sanitary napkins, surgical dressings, bandages, and the like, comprising a conveyor having a plurality of spaced trays thereon and onto which the articles are adapted to be placed, a plurality of forming dies disposed alongside the conveyor having the trays thereon, means for transferring a given number of the articles from the trays to a like number of the forming dies, each article being transferred to a separate forming die, means entering each of the forming dies for folding each of the articles upon itself, compressing means movable into the forming dies to compress and form the articles into an elongated mass, a rotary turret having a plurality of sets of bores disposed along its periphery, means for imparting a partial revolution at a time to the turret, means for feeding tubular cartons into one of the sets of bores, there being a single carton fed into each of the bores, means for ejecting each of the compressed articles from the forming dies into a corresponding carton disposed in each of said bores, means for ejecting the cartons from the bores

after the turret has moved away from the position where it received the articles into the cartons, means for cleaning the bores of any waste matter after the cartons have been ejected therefrom, the ends of the cartons being restricted to prevent expansion of the compressed article beyond the ends of the carton.

41. In a structure according to claim 40, the means for imparting step by step rotation to the turret comprising a Geneva stop mechanism for driving the turret to impart a partial revolution thereto for each revolution of the Geneva stop mechanism.

42. In a structure according to claim 40, the turret being square in elevation and having a plurality of bores disposed in a straight line on each of the four sides thereof which are adapted to align with the plurality of forming dies and whereby a plurality of cartons can be placed into the plurality of bores on one side of the turret and a plurality of articles can be moved into the cartons in the turret and compressed in the cartons.

43. In a structure according to claim 40, wherein the conveyor having the trays thereon is moved continuously and the means for moving the articles off the trays into the forming dies are moved intermittently, and in which the means for longitudinally compressing the articles in the forming dies and ejecting them into the cartons disposed within the turret are moved intermittently.

44. In a structure according to claim 40, the means for transferring the articles from the trays to the forming dies being adapted to move along the bottom of said trays and guiding means for raising the transferring means from off the bottom of the trays so that the transferring means will return at a higher elevation than that occupied while transferring the articles from the trays to the forming dies.

45. Apparatus for compressing and placing in suitable cartons having a restricted open end, fibrous articles such as sanitary napkins, surgical dressings and the like, comprising at least one die having a substantially U-shaped trough therein, means for compressing the article in said trough laterally, confining means for each carton disposed in alignment with one end of said trough, means for compressing the article in said trough longitudinally, and forcing the same under compression into the carton, said confining means confining the lateral portions of the carton while receiving the article, means for closing one end of the carton while the article is forced into the other end of the carton under compression, means for ejecting the carton from the confining means, and means for removing waste matter from the confining means after the carton has been ejected therefrom.

46. In a structure according to claim 45, said confining means including a member having bores therein for confining said cartons, the means for removing waste matter from the confining means comprising a plurality of nozzles aligned with the bores and means for forcing a blast of air through each of the nozzles to project the blasts of air through the bores to remove waste matter therefrom.

47. Apparatus for compressing and placing in suitable cartons, each having a restricted open end, fibrous articles such as sanitary napkins, surgical dressings and the like, comprising a plurality of dies, each die having a substantially U-shaped trough therein, means for folding the articles in the dies longitudinally, there being one article for each of the dies, means for compressing the articles in the dies laterally, confining means for each carton disposed in alignment with one end of each trough in said dies, means for compressing each of the articles in the dies longitudinally, and forcing the same under compression into the carton having a restricted open end while the carton is in the confining means, means for closing one end of the cartons while the articles are forced into the other ends of the cartons under compression, means for ejecting the cartons from the confining

means, and means for removing waste matter from the confining means after the cartons have been ejected therefrom.

48. In a structure according to claim 47, the carton confining means comprising a turret mounted for rotary movement and having a plurality of bores therein and means for moving the turret one step at a time to align a bore with the folding and compressing means and the means for removing waste material from the bore comprising a nozzle in alignment with a bore after a carton has been ejected from the bore for projecting a stream of compressed air through the bore to remove foreign matter therefrom.

49. Apparatus for compressing and placing in suitable open-ended cartons fibrous articles such as sanitary napkins, surgical dressings and the like comprising a plurality of dies, each having a substantially U-shaped trough therein, means for folding the articles in the dies along a line parallel to the direction of displacement of the fibres in the article, there being one article in each of the dies, means for compressing each of the articles in the dies laterally, confining means for each carton disposed in alignment with one end of each trough in said dies, means for compressing each of the articles in the dies longitudinally, and forcing the same under compression into the open end of the corresponding carton while the lateral portions of the carton are confined by the confining means, means for closing one end of the carton while the article is forced into the other end of the carton under compression, means for ejecting the carton from the confining means, and means for removing waste matter from the confining means after the cartons have been ejected therefrom.

50. In a structure according to claim 49, the carton confining means comprising a turret mounted for rotary movement and having a plurality of bores therein and means for moving the turret one step at a time to align a bore with the folding and compressing means and the means for removing waste material from the bore comprising a nozzle in alignment with a bore after a carton has been ejected from the bore for projecting a stream of compressed air through the bore to remove foreign matter therefrom.

51. Apparatus for compressing and placing in suitable open-ended cartons fibrous articles such as sanitary napkins, surgical dressings and the like having the fibres thereof extending longitudinally of the same, comprising a plurality of dies, each having a substantially U-shaped trough therein, means for compressing the articles in the dies laterally, confining means for each carton disposed in alignment with one end of each trough in said dies, means for compressing each of the articles in the dies longitudinally, and forcing the same under compression into the corresponding open end of the carton while the lateral portions of the carton are confined by the confining means, means for closing one end of the carton while the article is forced into the other end of the carton under compression, means for ejecting the carton from the confining means, and means for removing waste matter from the confining means after the cartons have been ejected therefrom, the compression imparted to the articles in placing the same in the cartons being short of the fatigue point of the fibres, so the articles will expand longitudinally when released from each of the cartons.

52. Apparatus for compressing and placing into tubular cartons fibrous articles such as sanitary napkins, surgical dressings, bandages and the like, comprising a plurality of side by side spaced forming dies, means for depositing an article into each of the forming dies, folding means for entering the forming dies and folding the articles longitudinally of the same, compressing means adapted to move alongside the folding means into the forming dies to compress the articles laterally to reduce their overall diameter, an intermittently movable mem-

ber having a plurality of sets of spaced bores therein, means for moving the member to present a plurality of bores in alignment with the longitudinal axes of the plurality of forming dies, a plurality of compressor means for entering one end of the forming dies and compressing the articles longitudinally and forcing the same into the bores in the movable member in alignment therewith, means for feeding an open-ended tubular carton into each bore previous to the time the articles are forced into the bores, and for closing the end of the bores through which the cartons are fed while the compressing means moves through the forming dies to eject the articles into the cartons in the bores, means for moving the member having the bores therein to move the bores having the cartons therein to another position and to present a new set of bores in alignment with the forming dies, means for entering the bores having the filled cartons therein for ejecting the filled cartons from their respective bores, means for moving the member having the bores therein to another position and means for removing waste material from the bores from which the filled cartons have previously been ejected.

53. Apparatus for compressing and placing into tubular open ended cartons fibrous articles such as sanitary napkins, surgical dressings, bandages and the like, comprising a plurality of side by side spaced open topped forming dies, means for depositing an article onto each of the forming dies, folding means for entering the open top of the forming dies and folding the articles longitudinally of the same, compressing means adapted to move alongside the folding means into the forming dies to compress the articles laterally to reduce their overall diameters, an intermittently movable member having a plurality of sets of spaced bores therein, means for moving the member to present a plurality of bores in alignment with the longitudinal axes of the plurality of forming dies, a plurality of compressor means for entering one end of the forming dies and compressing the articles longitudinally and forcing the same into the bores in the movable member in alignment therewith, means for feeding an open-ended tubular carton into each bore previous to the time the articles are forced into the bores and for closing the end of the bores through which the cartons are fed while the compressing means moves through the forming dies to eject the articles from the forming dies into the cartons in the bores, means for moving the member having the bores therein to move the bores having the cartons therein to another position and to present a new set of bores in alignment with the forming dies, means for entering the bores having the filled cartons therein for ejecting the filled cartons from their respective bores, and means for moving the member having the bores therein to another position and means for removing waste material from the bores from which the filled cartons have previously been ejected.

54. Apparatus for compressing and placing into tubular cartons fibrous articles such as sanitary napkins, surgical dressings, bandages and the like, comprising a plurality of side by side, spaced forming dies, means for depositing an article into each of the forming dies, folding means for entering the forming dies and folding the articles longitudinally of the same, compressing means adapted to move alongside the folding means into the forming dies to compress the articles laterally to reduce their overall diameters, an intermittently movable member having a plurality of sets of spaced bores therein, means for moving the member to present a plurality of bores in alignment with the longitudinal axes of the plurality of forming dies, a plurality of compressor means for entering one end of the forming dies and compressing the articles longitudinally and forcing the same into the bores in the movable member in alignment therewith, means for feeding an open-ended tubular carton into each bore previous to the time the articles are forced into the bores, and for closing the end of the bores

through which the cartons are fed while the compressing means moves through the forming dies to eject the articles into the cartons in the bores, means for moving the member having the bores therein to move the bores having the cartons therein to another position and to present a new set of bores in alignment with the forming dies and means for entering the bores having the filled cartons therein for ejecting the filled cartons from their respective bores.

55. Apparatus for compressing and placing into tubular cartons, having at least one open end, fibrous articles such as sanitary napkins, surgical dressings, bandages and the like, comprising a plurality of side by side spaced forming dies each having one side open, means for depositing an article onto the open side of each of the forming dies, folding means for entering the forming dies and folding the articles longitudinally of the same, compressing means adapted to move alongside the folding means into the forming dies to compress the articles laterally to reduce their overall diameter, an intermittently movable member having a plurality of sets of spaced bores therein, means for moving the member to present a plurality of bores in alignment with the longitudinal axes of the plurality of forming dies, a plurality of compressor means for entering one end of the forming dies and compressing the articles longitudinally and forcing the same into the bores in the movable member in alignment therewith, means for feeding a carton open end first into each bore previous to the time the articles are forced into the bores, and for closing one end of the bores through which the cartons are fed while the compressing means moves through the forming dies to eject the articles into the cartons in the bores, means for moving the member having the bores therein to cause the bores having the cartons therein to occupy another position and to present a new set of bores in alignment with the forming dies, means for ejecting the filled cartons from their respective bores, and means for moving the member having the bores therein to another position and means for removing waste material from the bores from which the filled cartons have previously been ejected.

56. A machine for folding, compressing and packaging fibrous articles such as sanitary napkins, surgical dressings and the like into a suitable open-ended confining carton, whose open end is restricted, comprising means for conveying a plurality of the articles spaced from each other, a fixed forming die disposed alongside the conveying means, means for transferring one of the articles from the conveying means to the forming die, means for entering the forming die and folding the article thereon midway of the same and longitudinally thereof, means for entering the die and compressing the article laterally into an elongated mass, a movable member having a plurality of spaced transverse bores therein whose ends are open, means for feeding a carton open end first into one of the bores, means for compressing the article longitudinally while under lateral compression in the forming die and ejecting the same into the carton while disposed in said bore, the means for feeding the carton into the bore remaining in position while the article is moved into the carton under longitudinal compression, means for moving the movable member to cause a bore coinciding with the forming die to move to another position and to present another bore in alignment with the forming die, means for ejecting the carton with the compressed article therein from the movable member while another carton is moved into another bore, and means for removing waste matter from the bore from which a carton with an article therein has been ejected.

57. Apparatus for folding and compressing a fibrous article such as a sanitary napkin, surgical dressing and the like into a tubular carton having two open ends and the inside dimensions of the ends of the carton being less than the other inside dimensions which comprises a die having a substantially U-shaped trough therein,

means for folding the article in the trough longitudinally upon itself, means for compressing the article while folded in the trough to preserve its overall length but diminishing its transverse thickness, a member having at least one bore therethrough disposed in alignment with one end of said trough, said bore being adapted to contain said carton, means for ejecting the article from the trough in the die and forcing it into the open-ended carton and exerting longitudinal pressure thereon to compress the same longitudinally in the carton and whereby the longitudinal compression will be captured by the restricted ends of the carton, and means for closing one end of the carton while the article is being forced thereinto through the other end.

58. Apparatus for folding a fibrous article upon itself and compressing the same and packaging the same under compression comprising a forming die above which the article is placed, means for moving the article laterally into the forming die to fold the same upon itself, means movable along each side of the folding means for compressing the article into the bottom of the forming die, a movable member having a bore therein disposed in alignment with the article while under compression in the forming die, means for placing a tubular container within the bore and holding one end thereof in closed position and means for ejecting the compressed article from the forming die and forcing it into the container and compressing it longitudinally to a longitudinal length less than the length of the container.

59. Apparatus for folding a fibrous article upon itself and compressing the same and packaging the same under compression comprising a forming die above which the article is placed, means for moving the article laterally into the forming die to fold the same upon itself, means movable along each side of the folding means for compressing the article into the bottom of the forming die, a movable member having a bore therein disposed in alignment with the article while under compression in the forming die, means for placing a tubular container within the bore and holding one end thereof in closed position, means for ejecting the compressed article from the forming die and forcing it into the container and compressing it longitudinally to a longitudinal length less than the length of the container, and means for moving the movable member to align another bore with the forming die.

60. In a machine for folding, compressing and packaging fibrous articles, such as sanitary napkins, surgical dressings, and the like, into a suitable confining carton, comprising means for conveying a plurality of the articles spaced from each other, a fixed forming die having an open side and open ends disposed alongside the conveying means, means for transferring one of the articles from the conveying means to the forming die, means for entering one side of the forming die for folding the article midway of the same and longitudinally thereof, means for entering the open side of the die and compressing the article laterally into an elongated mass, a movable member having a plurality of bores therein, means for feeding a carton, open at each end, into a bore, means for compressing the article longitudinally while under lateral compression in the forming die and ejecting the same into the carton while disposed in one of said bores, the means for feeding the carton into the bore remaining in position while the article is moved into the carton by the means for compressing the article longitudinally, means for moving the movable member to cause the bore coinciding with the forming die to move to another position and to present another bore in alignment with the forming die, means for ejecting the carton with the article therein from the first-named bore in the movable member while another carton is moved into another bore in the movable member, and means for removing waste matter from the bore from which a carton has been ejected.

- 42
61. In a machine for folding, compressing and packaging fibrous articles, such as sanitary napkins, surgical dressings and the like, into a confining carton having one end open, comprising means for conveying a plurality of the articles spaced from each other, a fixed forming die disposed alongside the conveying means, means for transferring one of the articles from the conveying means to the forming die, means for entering the forming die and folding the article midway of the same and longitudinally thereof, means for entering the die and compressing the article laterally into an elongated mass, a movable member having spaced open-ended bores therein, means for feeding a carton open end first into one of the bores, means for compressing the article longitudinally while under lateral compression in the forming die, and ejecting the same into the carton while disposed in said bore, the means for feeding the carton into the bore remaining in position while the article is moved into the carton under longitudinal compression, means for moving the movable member to cause the bore coinciding with the forming die to move to another position and to present another bore in alignment with the forming die, means for ejecting the carton with the compressed article therein from the first-named bore in the movable member while another carton is moved into another bore, and means for removing waste matter from the bore from which a carton has been ejected.
62. In a machine for folding, compressing and packaging fibrous articles, such as sanitary napkins, surgical dressings and the like, into a confining carton having one end open, comprising means for conveying a plurality of the articles spaced from each other, a fixed forming die having an open side and two open ends disposed alongside the conveying means, means for transferring one of the articles from the conveying means to the open side of the forming die, means for entering the open side of the forming die and folding the article midway of the same and longitudinally thereof, means for entering the open side of the die and compressing the article laterally into an elongated mass, a movable member having a plurality of spaced open ended-bores therein, means for feeding a carton open end first into one of the bores, means for entering one of the open ends of the forming die for compressing the article longitudinally while under lateral compression in the forming die, and ejecting the same into the carton while disposed in one of said bores, the means for feeding the carton into the bore remaining in position while the article is moved into the carton under longitudinal compression, means for moving the movable member to cause the bore coinciding with the forming die to move to another position and to present another bore in alignment with the forming die, means for ejecting the carton with the compressed article therein from the first-named bore in the movable member while another carton is moved into another bore, and means for removing waste matter from the bore from which a carton has been ejected.
63. In a machine for folding, compressing and packaging fibrous articles such as sanitary napkins, surgical dressings and the like into a suitable confining carton, comprising means for conveying a plurality of the articles spaced from each other, a fixed forming die disposed alongside the conveying means, means for transferring an article from the conveying means to the forming die, means for entering the forming die and folding the article midway of the same and longitudinally thereof, means for entering the die and compressing the article laterally into an elongated mass, a movable member having a plurality of spaced transverse bores therein, means for feeding a carton open at each end into a bore, means for compressing the article longitudinally while under lateral compression in the forming die and ejecting the same into the carton while disposed in said bore, the means for feeding the carton into the bore remaining in position while the article is moved into the carton under longitudi-

dinal compression, means for moving the movable member to cause the bore coinciding with the forming die to move to another position and to present another bore in alignment with the forming die, means for ejecting the carton with the compressed article therein from the movable member while another carton is moved into another bore, and means for removing waste matter from the bore from which a carton has been ejected.

64. A machine for folding, compressing and packaging fibrous articles, such as sanitary napkins, surgical dressings, and the like, in a suitable confining carton, comprising means for conveying a plurality of the articles spaced from each other, a plurality of fixed forming dies each having an open side and open ends disposed alongside the conveying means, means for transferring simultaneously a given number of the articles from the conveying means to a like number of the forming dies, each article being transferred to a separate forming die, means for entering one side of each of the forming dies and folding the articles midway of the same and longitudinally thereof, means for entering the open sides of the dies and compressing the articles laterally into an elongated mass, a movable member having a plurality of sets of open-ended bores therein, means for feeding a plurality of cartons open at each end into the bores in a given set, there being a single carton fed into each of the bores, and means for compressing the articles longitudinally while under lateral compression in the forming dies and ejecting one of the same into each of the cartons while disposed in said bores.

65. In a structure according to claim 64, each end of the carton being open and being of smaller inside diameter than the remainder of the carton to thereby capture and confine the longitudinal compression in the article disposed within the carton.

66. In a structure according to claim 64, the forming dies each having a substantially U-shaped trough extending longitudinally thereof which is open at its upper end, the folding means comprising a blade movable downwardly centrally of the trough to fold the articles longitudinally in face to face relation and the compressing means being adapted to move downwardly on each side of the blade and means for retracting the folding means while the forming and compressing means are moving downwardly into the U-shaped troughs.

67. A machine for folding, compressing and packaging fibrous articles, such as sanitary napkins, surgical dressings, and the like, in a suitable confining carton, comprising means for conveying a plurality of the articles spaced from each other, a plurality of fixed forming dies each having an open side and open ends disposed alongside the conveying means, means for transferring simultaneously a given number of the articles from the conveying means to a like number of the forming dies, each article being transferred to a separate forming die, means for entering one side of each of the forming dies and folding the articles midway of the same and longitudinally thereof, means for entering the open sides of the dies and compressing the articles laterally into an elongated mass, a movable member having a plurality of sets of open-ended bores therein, means for feeding a plurality of cartons open at each end into the bores in a given set, there being a single carton fed into each of the bores, and means for compressing the articles longitudinally while under lateral compression in the forming dies and ejecting one of the same into each of the cartons while disposed in said bores, the means for feeding the cartons into the bores remaining in position while the articles are moved into the cartons by the means for compressing the articles longitudinally.

68. A machine for folding, compressing and packaging fibrous articles, such as sanitary napkins, surgical dressings, and the like, in a suitable confining carton, comprising means for conveying a plurality of the articles spaced from each other, a plurality of fixed forming dies

each having an open side and open ends disposed alongside the conveying means, means for transferring simultaneously a given number of the articles from the conveying means to a like number of the forming dies, each

5 article being transferred to a separate forming die, means for entering one side of each of the forming dies and folding the articles midway of the same and longitudinally thereof, means for entering the open sides of the dies and compressing the articles laterally into an elongated mass, 10 a movable member having a plurality of sets of open-ended bores therein, means for feeding a plurality of cartons open at each end into the bores in a given set, there being a single carton fed into each of the bores, means for compressing the articles longitudinally while 15 under lateral compression in the forming dies and ejecting one of the same into each of the cartons while disposed in said bores, the means for feeding the cartons into the bores remaining in position while the articles are moved into the cartons by the means for compressing the 20 articles longitudinally, and means for moving the movable member to cause the set of bores coinciding with the forming dies to move to another position and to present another set of bores in alignment with the forming dies.

69. A machine for folding, compressing and packaging 25 fibrous articles, such as sanitary napkins, surgical dressings, and the like, in a suitable confining carton, comprising means for conveying a plurality of the articles spaced from each other, a plurality of fixed forming dies each having an open side and open ends disposed alongside 30 the conveying means, means for transferring simultaneously a given number of the articles from the conveying means to a like number of the forming dies, each article being transferred to a separate forming die, means for entering one side of each of the forming dies and folding 35 the articles midway of the same and longitudinally thereof, means for entering the open sides of the dies and compressing the articles laterally into an elongated mass, a movable member having a plurality of sets of open-ended bores therein, means for feeding a plurality of 40 cartons open at each end into the bores in a given set, there being a single carton fed into each of the bores, means for compressing the articles longitudinally while under lateral compression in the forming dies and ejecting one of the same into each of the cartons while disposed in said bores, the means for feeding the cartons into the 45 bores remaining in position while the articles are moved into the cartons by the means for compressing the articles longitudinally, means for moving the movable member to cause the set of bores coinciding with the forming dies to move to another position and to present another set of bores in alignment with the forming dies and means for ejecting the cartons with the compressed articles therein from the movable member, while another set of cartons is moved into another set of bores.

50 70. A machine for folding, compressing and packaging fibrous articles, such as sanitary napkins, surgical dressings, and the like, in a suitable confining carton, comprising means for conveying a plurality of the articles spaced from each other, a plurality of fixed forming dies disposed alongside the conveying means, means for transferring simultaneously a given number of the articles from the conveying means to the forming dies, each article being transferred to a separate forming die, means for entering the forming dies and folding the articles 55 midway of the same and longitudinally thereof, means for entering the dies and compressing the articles laterally into an elongated mass, a movable member having a plurality of sets of open ended bores therein, means for feeding a plurality of cartons open at each end into the 60 bores in a given set, there being a single carton fed into each of the bores, and means for compressing the articles longitudinally while under lateral compression in the forming dies and ejecting one of the same into each of the cartons while disposed in said bores, the means for feeding the cartons into the bores remaining in position 65 70 75

while the articles are moved into the cartons under longitudinal compression.

71. In a structure according to claim 70, the forming dies each having a substantially U-shaped trough extending longitudinally thereof which is open at its upper end, the folding means comprising a blade movable downwardly centrally of the trough to fold the articles longitudinally in face to face relation and the compressing means being adapted to move downwardly on each side of the blade and means for retracting the folding means while the forming and compressing means are moving downwardly into the U-shaped troughs.

72. A machine for folding, compressing and packaging fibrous articles, such as sanitary napkins, surgical dressings, and the like, in a suitable confining carton, comprising means for conveying a plurality of the articles spaced from each other, a plurality of fixed forming dies disposed alongside the conveying means, means for transferring simultaneously a given number of the articles from the conveying means to a like number of the forming dies, each article being transferred to a separate forming die, means for entering the forming dies and folding the articles midway of the same and longitudinally thereof, means for entering the dies and compressing the articles laterally into an elongated mass, a movable member having a plurality of sets of open ended bores therein, means for feeding a plurality of cartons open at each end into the bores in a given set, there being a single carton fed into each of the bores, means for compressing the articles longitudinally while under lateral compression in the forming dies and ejecting one of the same into each of the cartons while disposed in said bores, the means for feeding the cartons into the bores remaining in position while the articles are moved into the cartons under longitudinal compression, means for moving the movable member to cause the set of bores coinciding with the forming dies to move to another position and to present another set of bores in alignment with the forming dies, and means for ejecting the cartons with the compressed articles therein from the movable member, while another set of cartons is moved into another set of bores.

73. A machine for folding, compressing and packaging fibrous articles, such as sanitary napkins, surgical dressings, and the like, in a suitable confining carton having one end open, comprising means for conveying a plurality of the articles spaced from each other, a plurality of fixed forming dies disposed alongside the conveying means, means for transferring simultaneously a given number of the articles from the conveying means to a like number of the forming dies, each article being transferred to a separate forming die, means for entering the forming dies and folding the articles midway of the same and longitudinally thereof, means for entering the dies and compressing the articles laterally into an elongated mass, a movable member having a plurality of sets of open-ended bores therein, means for feeding a plurality of cartons, open end first into the bores in a given set, there being a single carton fed into each of the bores, and means for compressing the articles longitudinally while under lateral compression in the forming dies and ejecting one of the same into each of the cartons while disposed in said bores, the means for feeding the cartons into the bores remaining in position while the article is moved into the carton under longitudinal compression.

74. In a structure according to claim 73, the forming dies each having a substantially U-shaped trough extending longitudinally thereof which is open at its upper end, the folding means comprising a blade movable downwardly centrally of the trough to fold the articles longitudinally in face to face relation and the compressing means being adapted to move downwardly on each side of the blade and means for retracting the folding means while the forming and compressing means are moving downwardly into the U-shaped troughs.

75. A machine for folding, compressing and packaging

fibrous articles, such as sanitary napkins, surgical dressings, and the like, in a suitable open-ended confining carton whose open end is restricted, comprising means for conveying a plurality of the articles spaced from each other, a plurality of fixed forming dies disposed alongside the conveying means, means for transferring simultaneously a given number of the articles from the conveying means to a like number of the forming dies, each article being transferred to a separate forming die, means for entering the forming dies and folding the articles midway of the same and longitudinally thereof, means for entering the dies and compressing the articles laterally into an elongated mass, a movable member having a plurality of sets of bores therein whose ends are open, means for feeding a plurality of cartons open end first into the bores in a given set, there being a single carton fed into each of the bores, means for compressing the articles longitudinally while under lateral compression in the forming dies and ejecting one of the same into each of the cartons while disposed in said bores, means for moving the movable member to cause the set of bores coinciding with the forming dies to move to another position and to present another set of bores in alignment with the forming dies, means for ejecting the cartons with the compressed articles therein from the movable member, while another set of cartons is moved into another set of bores, and means for removing waste matter from the bores from which a plurality of cartons have been ejected.

76. In a structure according to claim 75, the forming dies each having a substantially U-shaped trough extending longitudinally thereof which is open at its upper end, the folding means comprising a blade movable downwardly centrally of the trough to fold the articles longitudinally in face to face relation and the compressing means being adapted to move downwardly on each side of the blade and means for retracting the folding means while the forming and compressing means are moving downwardly into the U-shaped troughs.

77. Apparatus for folding and compressing a fibrous article such as a sanitary napkin and depositing the same under compression in a suitable container comprising at least one forming die having a substantially U-shaped trough therein, means for folding the article into said trough longitudinally of itself, means for compressing the article laterally in said trough to reduce its thickness, means for holding an open-ended container adjacent one end of said trough, means for compressing the article longitudinally while held under lateral compression and ejecting the same from the trough into the container and compressing the article to an overall length of less than that of the container, means for moving the holding means for the container to another position and presenting a new holding means adjacent said end of the trough, means for ejecting the container having the compressed article therein from the holding means, while another article is being forced into another container in the holding means, and means for removing waste from the holding means from which a container has been ejected.

78. Apparatus for folding and compressing a fibrous article such as a sanitary napkin and depositing the same under compression in a suitable container comprising at least one forming die having a substantially U-shaped trough therein, means for folding the article into said trough longitudinally of itself, means for compressing the article laterally in said trough to reduce its thickness, means for holding an open-ended container adjacent one end of said trough, means for compressing the article longitudinally while held under lateral compression and ejecting the same from the trough into the container and compressing the article to an overall length of less than that of the container, said container having a restricted open end through which the article is forced into the container to thus retain the article within the carton, means for moving the holding means for the container to another position and presenting a new holding means ad-

jaçent said end of the trough, and means for ejecting the container having the compressed article therein from the holding means, while another article is being forced into another container in the holding means.

79. Apparatus for folding and compressing a fibrous article such as a sanitary napkin and depositing the same under compression in a suitable open-ended carton comprising at least one forming die having a substantially U-shaped trough therein, means for folding the article into said trough longitudinally of itself, means for compressing the article laterally in said trough to reduce its overall diameter, means for holding an open-ended carton adjacent one end of said trough, means for compressing the article longitudinally while held under lateral compression and ejecting the same from the trough into the carton and compressing the article to an overall length of less than that of the carton, said carton being restricted at the end through which the article is forced into the carton to thus retain the article under compression within the carton, means for moving the holding means for the carton to another position and presenting a new holding means adjacent said end of the trough, and means for ejecting the carton having the compressed article therein from the holding means.

80. In a structure according to claim 79, the carton being tubular and open at both ends and having each end thereof restricted to capture and hold the compression in the article which is placed into the carton in compressed condition.

81. Apparatus for folding and compressing a fibrous article, having the fibres extending longitudinally thereof, such as a sanitary napkin and depositing the same under longitudinal compression in a suitable open-ended carton comprising at least one forming die having a substantially U-shaped trough therein, means for folding the article into the trough longitudinally of itself, means for compressing the article laterally in said trough to reduce its overall diameter, means for holding an open-ended carton adjacent one end of the trough, means for compressing the article longitudinally while held under lateral compression and ejecting the same from the trough into the carton and compressing the article to an overall length of less than that of the carton, said carton being restricted at its end through which the article is forced into the carton to thus retain the article within the carton, means for moving the holding means for the carton to another position and presenting a new holding means adjacent the end of the trough, and means for ejecting the carton having the compressed article therein from the holding means, while another article is being forced into another carton in the holding means.

82. In a structure according to claim 81, the carton being tubular and open at both ends and having each end thereof restricted to capture and hold the compression in the article which is placed into the carton in compressed condition.

83. Apparatus for compressing and placing in suitable cartons fibrous articles such as sanitary napkins, surgical dressings, bandages, and the like, comprising a conveyor having a plurality of spaced trays thereon and onto which the articles are adapted to be placed, a plurality of forming dies disposed alongside the conveyor having the trays thereon, means for transferring a given number of the articles from the trays to a like number of the forming dies, each article being transferred to a separate forming die, means entering each of the forming dies for folding the articles upon themselves, compressing means movable into each of the forming dies to compress and form the articles into an elongated mass, a turret having a plurality of sets of bores disposed along its periphery, means for imparting step-by-step movement to the turret, means for feeding tubular cartons into a set of bores, there being a single carton fed into each of the bores, means for ejecting one of the compressed articles from the forming dies into each of the cartons disposed in said bores,

and means for ejecting the cartons from the bores after the turret has moved away from the position where it received the articles into the cartons.

84. In a structure according to claim 83, each end of the carton being open and being of smaller inside diameter than the remainder of the carton to thereby capture and confine the longitudinal compression in the article disposed within the container.

85. In a structure according to claim 83, the means for imparting step-by-step partial rotation to the turret comprising a Geneva stop mechanism for driving the turret to impart a partial rotation thereto for each revolution of the Geneva stop mechanism.

86. In a structure according to claim 83, the means for feeding the cartons into the turret comprising a plurality of vertically disposed magazines having aligned openings in opposed sides thereof, means for feeding the cartons into the magazine, plungers for passing through the aligned openings and removing the lowermost carton and forcing it into a bore, means for moving the plungers through the aligned openings in the magazines and forcing the cartons into the bores and remaining in position to close that end of the cartons while the ejecting means moves the articles from the corresponding forming dies into the cartons disposed in the bores in the turret.

87. In a structure according to claim 83, the turret being square in elevation and having a plurality of bores disposed in a straight line on each of the four sides thereof which are adapted to align with the plurality of forming dies and whereby one of a plurality of cartons can be placed into each of the plurality of bores on one side of the turret and one of a plurality of articles can be moved into each of the cartons in the turret and compressed in the cartons.

88. Apparatus for compressing and placing in suitable cartons fibrous articles such as sanitary napkins, surgical dressings, bandages, and the like, comprising a conveyor having a plurality of spaced trays thereon and onto which the articles are adapted to be placed, a plurality of forming dies disposed alongside the conveyor having the trays thereon, means for transferring a given number of the articles from the trays to a like number of the forming dies, each article being transferred to a separate forming die, means entering the forming dies for folding the articles upon themselves, compressing means movable into each of the forming dies to compress and form the articles into an elongated mass, a turret having a plurality of sets of bores disposed along its periphery, means for imparting step-by-step movement to the turret, means for feeding tubular cartons into a set of bores, there being a single carton fed into each of the bores, means for ejecting one of the compressed articles from the forming dies into each of the cartons disposed in said bores, means for ejecting the cartons from the bores after the turret

50 has moved away from the position where it received the articles into the cartons, and means for conveying the ejected cartons away from the machine after they have been ejected from the turret.

89. Apparatus for compressing and placing in suitable cartons fibrous articles such as sanitary napkins, surgical dressings, bandages, and the like, comprising a conveyor having a plurality of spaced trays thereon and onto which the articles are adapted to be placed, a plurality of forming dies disposed alongside the conveyor having the trays

65 thereon, means for transferring a given number of the articles from the trays to a like number of the forming dies, each article being transferred to a separate forming die, means entering each of the forming dies for folding each of the articles upon itself, compressing means movable into the forming dies to compress and form the articles into an elongated mass, a rotary turret having a plurality of sets of transverse bores disposed along its periphery, means for imparting step-by-step movement to the turret, means for feeding tubular cartons into the bores, there being a single carton fed into each of the

bores, means for ejecting one of the compressed articles from the forming dies into each of the cartons disposed in said bores and compressing the articles to a length which is less than the length of the cartons, and means for ejecting the cartons from the bores after a set of bores in the turret has moved away from the position where it received the articles into the cartons.

90. In a structure according to claim 89, the means for imparting step-by-step partial rotation to the turret comprising a Geneva stop mechanism for driving the turret to impart a partial rotation thereto for each revolution of the Geneva stop mechanism.

91. In a structure according to claim 89, each end of the carton being open and being of smaller inside diameter than the remainder of the carton to thereby capture and confine the longitudinal compression in the article disposed within the carton.

92. In a structure according to claim 89, the means for feeding the cartons into the turret comprising a plurality of vertically disposed magazines having aligned openings in opposed sides thereof, means for feeding the cartons into the magazine, plungers for passing through the aligned openings and removing the lowermost carton and forcing it into a bore, means for moving the plungers through the aligned openings in the magazines and forcing the cartons into the bores and remaining in position to close that end of the cartons while the ejecting means moves the articles from the corresponding forming dies into the cartons disposed in the bores in the turret.

93. In a structure according to claim 89, the turret being square in elevation and having a plurality of bores disposed in a straight line on each of the four sides thereof which are adapted to align with the plurality of forming dies and whereby one of a plurality of cartons can be placed into each of the plurality of bores on one side of the turret and one of a plurality of articles can be moved into each of the cartons in the turret and compressed in the cartons.

94. In a structure according to claim 89, the turret being square in elevation and having a plurality of bores along each of the four edges thereof and the means for imparting rotation to the turret in step-by-step relation moving the turret a quarter revolution at a time to align the bores in one of the four side edges of the turret with the plurality of forming dies for the reception of the compressed articles from the forming dies.

95. In a structure according to claim 89, wherein the conveyor having the trays thereon is moved continuously and the means for moving the articles off the trays into the forming dies are moved intermittently, and in which the means for longitudinally compressing the articles in the forming dies and ejecting them into the containers disposed within the turret are moved intermittently.

96. In a structure according to claim 89, the means for transferring the articles from the trays to the forming dies being adapted to move along the bottom of said trays and guiding means for raising the transferring means from off the bottom of the trays so that the transferring means will return at a higher elevation than that occupied while transferring the articles from the trays to the forming dies.

97. Apparatus for compressing and placing in suitable cartons fibrous articles such as sanitary napkins, surgical dressings, bandages, and the like, comprising a conveyor having a plurality of spaced trays thereon and onto which the articles are adapted to be placed, a plurality of forming dies disposed alongside the conveyor having the trays thereon, means for transferring a given number of the articles from the trays to a like number of the forming dies, each article being transferred to a separate forming die, means entering each of the forming dies for folding each of the articles upon itself, compressing means movable sidewise into the forming dies to compress and form the articles into an elongated mass, a movable turret having a plurality of sets of transverse bores disposed therethrough, means for imparting step-by-step movement

to the turret, means for feeding tubular open-ended cartons into a given set of the bores, there being a single carton fed into each of the bores, means for ejecting each of the compressed articles from the forming dies into a corresponding one of the cartons disposed in said bores through an open end thereof, and means for ejecting the cartons from the bores after the turret has moved away from the position where it received the articles into the cartons.

98. In a structure according to claim 97, wherein the conveyor having the trays disposed thereon is moved continuously and the means for moving the articles off the trays into the forming dies are moved intermittently, and in which the means for longitudinally compressing the articles in the forming dies and ejecting them into the cartons disposed within the turret are moved intermittently.

99. In a structure according to claim 97, the means for transferring the articles from the trays to the forming dies being adapted to move along the bottom of said trays and guiding means for raising the transferring means from off the bottom of the trays so that the transferring means will return at a higher elevation than that occupied while transferring the articles from the trays to the forming dies.

100. Apparatus for compressing and placing in tubular open-ended cartons fibrous articles such as sanitary napkins, surgical dressings, bandages, and the like, comprising a conveyor having a plurality of spaced trays thereon and onto which the articles are adapted to be placed, a plurality of forming dies disposed alongside the conveyor having the trays thereon, means for transferring a given number of the articles from the trays to a like number of the forming dies, each article being transferred to a separate forming die, means entering each of the forming dies

30 for folding each of the articles upon itself, compressing means movable into the forming dies to compress and form the articles into an elongated mass, a rotary turret having a plurality of sets of bores disposed along its periphery, means for imparting a partial revolution at a time

40 to the turret, means for feeding tubular cartons into one of the sets of bores, there being a single carton fed into each of the bores, means for ejecting each of the compressed articles from the forming dies into a corresponding carton disposed in each of said bores, and means for ejecting the cartons from the bores after the turret has moved away from the position where it received the articles into the cartons.

101. In a structure according to claim 100, the means for imparting step-by-step rotation to the turret comprising a Geneva stop mechanism for driving the turret to impart a partial revolution thereto for each revolution of the Geneva stop mechanism.

102. In a structure according to claim 100, the turret being square in elevation and having a plurality of bores disposed in a straight line on each of the four sides thereof which are adapted to align with the plurality of forming dies and whereby a plurality of cartons can be placed into the plurality of bores on one side of the turret and a plurality of articles can be moved into the cartons in the turret and compressed in the cartons.

103. In a structure according to claim 100, wherein the conveyor having the trays thereon is moved continuously and the means for moving the articles off the trays into the forming dies are moved intermittently, and in which the means for longitudinally compressing the articles in the forming dies and ejecting them into the cartons disposed within the turret are moved intermittently.

104. In a structure according to claim 100, the means for transferring the articles from the trays to the forming dies being adapted to move along the bottom of said trays and guiding means for raising the transferring means from off the bottom of the trays so that the transferring means will return at a higher elevation than that occupied while transferring the articles from the trays to the forming dies.

105. In a structure according to claim 100, the means for transferring the articles from the trays to the forming dies being adapted to move along the bottom of said trays and guiding means for raising the transferring means from off the bottom of the trays so that the transferring means will return at a higher elevation than that occupied while transferring the articles from the trays to the forming dies.

106. In a structure according to claim 100, the means for transferring the articles from the trays to the forming dies being adapted to move along the bottom of said trays and guiding means for raising the transferring means from off the bottom of the trays so that the transferring means will return at a higher elevation than that occupied while transferring the articles from the trays to the forming dies.

105. Apparatus for compressing and placing in suitable cartons having a restricted open end, fibrous articles such as sanitary napkins, surgical dressings and the like, comprising at least one die having a substantially U-shaped trough therein, means for compressing the article in said trough laterally, confining means for each carton disposed in alignment with one end of said trough, means for compressing the article in said trough longitudinally, and forcing the same under compression into the carton, said confining means confining the lateral portions of the carton while receiving the article, means for closing one end of the carton while the article is forced into the other end of the carton under compression, and means for ejecting the carton from the confining means.

106. Apparatus for compressing and placing in suitable cartons, each having a restricted open end, fibrous articles such as sanitary napkins, surgical dressings and the like, comprising a plurality of dies, each die having a substantially U-shaped trough therein, means for folding the articles in the dies longitudinally, there being one article for each of the dies, means for compressing each of the articles in the dies laterally, confining means for each carton disposed in alignment with one end of each trough in said dies, means for compressing each of the articles in the dies longitudinally, and forcing the same under compression into the carton having a restricted open end while the carton is in the confining means, means for closing one end of the cartons while the articles are forced into the other ends of the cartons under compression, and means for ejecting the cartons from the confining means.

107. Apparatus for compressing and placing in suitable open-ended cartons fibrous articles such as sanitary napkins, surgical dressings and the like comprising a plurality of dies, each having a substantially U-shaped trough therein, means for folding the articles in the dies along a line parallel to the direction of displacement of the fibres in the article, there being one article in each of the dies, means for compressing each of the articles in the dies laterally, confining means for each carton disposed in alignment with one end of each trough in said dies, means for compressing each of the articles in the dies longitudinally, and forcing the same under compression into the open end of the corresponding carton while the lateral portions of the carton are confined by the confining means, means for closing one end of the carton while the article is forced into the other end of the carton under compression, and means for ejecting the carton from the confining means.

108. In a structure according to claim 107, the carton confining means comprising a turret mounted for rotary movement and having a plurality of bores therein and means for moving the turret one step at a time to align a bore with the folding and compressing means.

109. Apparatus for compressing and placing in suitable open-ended cartons fibrous articles such as sanitary napkins, surgical dressings and the like having the fibres thereof extending longitudinally of the same, comprising a plurality of dies, each having a substantially U-shaped trough therein, means for compressing the articles in the dies laterally, confining means for each carton disposed in alignment with one end of each trough in said dies, means for compressing each of the articles in the dies longitudinally, and forcing the same under compression into the open end of the corresponding carton while the lateral portions of the carton are confined by the confining means, means for closing one end of the carton while the article is forced into the other end of the carton under compression, and means for ejecting the carton from the confining means, the compression imparted to the articles in placing the same in the cartons being short of the fatigue point of the fibres, so the articles will expand longitudinally when released from each of the cartons.

110. Apparatus for compressing and placing into tubular cartons fibrous articles such as sanitary napkins, surgical dressings, bandages and the like, comprising a plu-

rality of side by side spaced forming dies, means for depositing an article into each of the forming dies, folding means for entering the forming dies and folding the articles longitudinally of the same, compressing means adapted to move alongside the folding means into the forming dies to compress the articles laterally to reduce their overall diameter, an intermittently movable member having a plurality of sets of spaced bores therein, means for moving the member to present a plurality of bores in alignment with the longitudinal axes of the plurality of forming dies, a plurality of compressor means for entering one end of the forming dies and compressing the articles longitudinally and forcing the same into the bores in the movable member in alignment therewith, means for feeding an open-ended tubular carton into each bore previous to the time the articles are forced into the bores, and for closing the end of the bores through which the cartons are fed while the compressing means moves through the forming dies to eject the articles into the cartons in the bores, means for moving the member having the bores therein to move the bores having the cartons therein to another position and to present a new set of bores in alignment with the forming dies, means for entering the bores having the filled cartons therein for ejecting the filled cartons from their respective bores, and means for moving the member having the bores therein to another position.

111. Apparatus for compressing and placing into tubular open-ended cartons fibrous articles such as sanitary napkins, surgical dressings, bandages and the like, comprising a plurality of side by side spaced open topped forming dies, means for depositing an article onto each of the forming dies, folding means for entering the open top of the forming dies and folding the articles longitudinally of the same, compressing means adapted to move alongside the folding means into the forming dies to compress the articles laterally to reduce their overall diameters, an intermittently movable member having a plurality of sets of spaced bores therein, means for moving the member to present a plurality of bores in alignment with the longitudinal axes of the plurality of forming dies, a plurality of compressor means for entering one end of the forming dies and compressing the articles longitudinally and forcing the same into the bores in the movable member in alignment therewith, means for feeding an open-ended tubular carton into each bore previous to the time the articles are forced into the bores and for closing the end of the bores through which the cartons are fed while the compressing means moves through the forming dies to eject the articles from the forming dies into the cartons in the bores, means for moving the member having the bores therein to move the bores having the cartons therein to another position and to present a new set of bores in alignment with the forming dies, means for entering the bores having the filled cartons therein for ejecting the filled cartons from their respective bores, and means for moving the member having the bores therein to another position.

112. Apparatus for compressing and placing into tubular cartons, having at least one open end, fibrous articles such as sanitary napkins, surgical dressings, bandages and the like, comprising a plurality of side by side spaced forming dies having one side open, means for depositing an article onto the open side of each of the forming dies, folding means for entering the forming dies and folding the articles longitudinally of the same, compressing means adapted to move alongside the folding means into the forming dies to compress the articles laterally to reduce their overall diameter, an intermittently movable member having a plurality of sets of spaced bores therein, means for moving the member to present a plurality of bores in alignment with the longitudinal axes of the plurality of forming dies, a plurality of compressor means for entering one end of the forming dies and compressing the articles longitudinally and

forcing the same into the bores in the movable member in alignment therewith, means for feeding a carton open end first into each bore previous to the time the articles are forced into the bores, and for closing the ends of the bores through which the cartons are fed while the compressing means moves through the forming dies to eject the articles into the cartons in the bores, means for moving the member having the bores therein to cause the bores having the cartons therein to occupy another position and to present a new set of bores in alignment with the forming dies, means for ejecting the filled cartons from their respective bores, and means for moving the member having the bores therein to another position.

113. A machine for folding, compressing and packaging fibrous articles such as sanitary napkins, surgical dressings and the like into a suitable open-ended confining carton, whose open end is restricted, comprising means for conveying a plurality of the articles spaced from each other, a fixed forming die disposed alongside the conveying means, means for transferring one of the articles from the conveying means to the forming die, means for entering the forming die and folding the article thereon midway of the same and longitudinally thereof, means for entering the die and compressing the article laterally into an elongated mass, a movable member having a plurality of spaced transverse bores therein whose ends are open, means for feeding a carton open end first into one of the bores, means for compressing the article longitudinally while under lateral compression in the forming die and ejecting the same into the carton while disposed in said bore, the means for feeding the carton into the bore remaining in position while the article is moved into the carton under longitudinal compression, means for moving the movable member to cause a bore coinciding with the forming die to move to another position and to present another bore in alignment with the forming die, and means for ejecting the carton with the compressed article therein from the movable member while another carton is moved into another bore.

114. In a machine for folding, compressing and packaging fibrous articles, such as sanitary napkins, surgical dressings, and the like, into a suitable confining carton, comprising means for conveying a plurality of the articles spaced from each other, a fixed forming die having an open side and open ends disposed alongside the conveying means, means for transferring one of the articles from the conveying means to the forming die, means for entering the open side of the forming die for folding the article midway of the same and longitudinally thereof, means for entering the open side of the die and compressing the article laterally into an elongated mass, a movable member having a plurality of bores therein, means for feeding a carton, open at each end, into a bore, means for compressing the article longitudinally while under lateral compression in the forming die and ejecting the same into the carton while disposed in one of said bores, the means for feeding the carton into the bore remaining in position while the article is moved into the carton by the means for compressing the article longitudinally, means for moving the movable member to cause the bore coinciding with the forming die to move to another position and to present another bore in alignment with the forming die, and means for ejecting the carton with the article therein from the first-named bore in the movable member while another carton is moved into another bore in the movable member.

115. In a machine for folding, compressing and packaging fibrous articles, such as sanitary napkins, surgical dressings and the like, into a confining carton having one end open, comprising means for conveying a plurality of the articles spaced from each other, a fixed forming die disposed alongside the conveying means, means for transferring one of the articles from the conveying means to the forming die, means for entering the forming die and folding the article midway of the same and longitudinally

thereof, means for entering the die and compressing the article laterally into an elongated mass, a movable member having spaced open-ended bores therein, means for feeding a carton open end first into one of the bores, means for compressing the article longitudinally while under lateral compression in the forming die, and ejecting the same into the carton while disposed in said bore, the means for feeding the carton into the bore remaining in position while the article is moved into the carton under longitudinal compression, means for moving the movable member to cause the bore coinciding with the forming die to move to another position and to present another bore in alignment with the forming die, and means for ejecting the carton with the compressed article therein from the first-named bore in the movable member while another carton is moved into another bore.

116. In a machine for folding, compressing and packaging fibrous articles, such as sanitary napkins, surgical dressings and the like, into a confining carton having one end open, comprising means for conveying a plurality of the articles spaced from each other, a fixed forming die having an open side and two open ends disposed alongside the conveying means, means for transferring one of the articles from the conveying means to the open side of the forming die, means for entering the open side of the forming die and folding the article midway of the same and longitudinally thereof, means for entering the open side of the die and compressing the article laterally into an elongated mass, a movable member having a plurality of spaced open-ended bores therein, means for feeding a carton open end first into one of the bores, means for entering one of the open ends of the forming die for compressing the article longitudinally while under lateral compression in the forming die, and ejecting the same into the carton while disposed in one of said bores, the means for feeding the carton into the bore remaining in position while the article is moved into the carton under longitudinal compression, means for moving the movable member to cause the bore coinciding with the forming die to move to another position and to present another bore in alignment with the forming die, and means for ejecting the carton with the compressed article therein from the first-named bore in the movable member while another carton is moved into another bore.

117. In a machine for folding, compressing and packaging fibrous articles such as sanitary napkins, surgical dressings and the like into a suitable confining carton, comprising means for conveying a plurality of the articles spaced from each other, a fixed forming die disposed alongside the conveying means, means for transferring an article from the conveying means to the forming die, means for entering the forming die and folding the article midway of the same and longitudinally thereof, means for entering the die and compressing the article laterally into an elongated mass, a movable member having a plurality of spaced transverse bores therein, means for feeding a carton open at each end into a bore, means for compressing the article longitudinally while under lateral compression in the forming die and ejecting the same into the carton while disposed in said bore, the means for feeding the carton into the bore remaining in position while the article is moved into the carton under longitudinal compression, means for moving the movable member to cause the bore coinciding with the forming die to move to another position and to present another bore in alignment with the forming die, and means for ejecting the carton with the compressed article therein from the movable member while another carton is moved into another bore.

118. Apparatus for folding a fibrous article upon itself and compressing the same and packaging the same under compression comprising a forming die above which the article is placed, said forming die having a longitudinally extending first bore therein which is circular in cross-section and having one of its walls provided with a slot extending from the first bore to the exterior of the die,

means for moving the article laterally through said slot and into the bore to fold the same upon itself, means movable into the slot along each side of the folding means for compressing the article into the bore of the forming die, a movable member having a second bore therein disposed in alignment with the article while under compression in the forming die, means for placing a tubular container within the second bore and holding one end thereof in closed position, means movable into and through the first bore for ejecting the compressed article from the first bore and forcing it into the container and compressing it longitudinally to a longitudinal length less than the length of the container, and means for moving the movable member to align another second bore with the forming die.

119. Apparatus for folding a fibrous article upon itself and compressing the same and packaging the same under compression comprising a forming die above which the article is placed, said forming die having a longitudinally extending first bore therein which is circular in cross-section and having one of its walls provided with a slot extending from the first bore to the exterior of the die, means for moving the article laterally of said slot and into said bore to fold the same upon itself, means movable along each side of the folding means to the junction point of the slot and the first bore for compressing the article in said first bore, a movable member having a second bore therein disposed in alignment with the article while under compression in the first bore, means for placing a tubular container within the second bore, means for ejecting the compressed article from the first bore and forcing it into the container and compressing it longitudinally to a longitudinal length less than the length of the container, and means for moving the movable member to align another second bore with the first bore in the forming die.

120. Apparatus for folding a fibrous article upon itself and compressing the same and packaging the same under compression comprising a forming die above which the article is placed, said forming die having a first bore therein and a slot extending from the first bore to the exterior of the forming die, means for moving the article

laterally of the forming die and through said slot and into the first bore in the forming die to fold the same upon itself, means movable through said slot along each side of the folding means for compressing the article into the first bore in the forming die, a movable member having a second bore therein disposed in alignment with the first bore while the article is under compression in the first bore, means for placing a tubular container within the second bore, means for temporarily closing one end of the carton while it is disposed in the second bore, means for ejecting the compressed article from the bore in the forming die and forcing it into the container and compressing it longitudinally to a longitudinal length less than the length of the container, and means for moving the movable member to align another second bore with the forming die.

121. Apparatus for folding a fibrous article and compressing the same and packaging the same under compression comprising a forming die having a first bore circular in cross-section and a slot communicating therewith and above which the article is placed, means for moving the article laterally through said slot and into the first bore to fold the same upon itself, means movable along each side of the folding means in said slot for compressing the article into the first bore of the forming die, a movable member having a second bore therein, means for moving the movable member to align its bore with the first bore, means for placing a tubular container within the second bore and holding one end thereof in closed position, means for ejecting the compressed article from the forming die and forcing it into the container and compressing it longitudinally to a longitudinal length less than the length of the container.
